UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TESTING DEVICE FOR TELEPHONE-EXCHANGE SYSTEMS.

Application filed December 22, 1922. Serial No. 608,430.

To all whom it may concern:

Be it known that I, ERIC R. LUNDIUS, a citizen of the United States of America, residing at Brooklyn, in the county of Kings and State of New York, have invented certain new and useful Improvements in Testing Devices for Telephone-Exchange Systems, of which the following is a full, clear, concise, and exact description.

10 This invention relates to a telephone exchange system, and more particularly, to a testing device for testing the selector switches employed in machine switching systems.

15 One of the principal requirements in the operation of a telephone exchange system operating either on a manual or mechanical basis, is that of maintaining the central office equipment in proper working condition.

20 In the case of manual exchanges the central office equipment is relatively simple and the problem of keeping such apparatus in good working order is a comparatively easy one. However in the case of mechanical offices,

25 the central office equipment is much more complicated, the establishment of different classes of calls bringing into operation in varying combinations selector mechanisms of various types, each of which affords opportunities for trouble to arise. The amount

30 of apparatus used in mechanical exchange systems is very large and much of it is made up of moving parts subject to loss of adjustment while in use or under repair. All apparatus of this nature, such as relays, interrupters, sequence switches, clutches and selector mechanisms must be watched to detect wear, or broken parts, or loss of adjustment which may be a result of a normal use of the equipment or the result of mistreatment. Naturally, the failure of any piece of apparatus to function properly will result in the stopping of the progress of calls or in the false routing of calls.

45 Such failures ordinarily would not be detected except where calls are repeatedly reported as incomplete, and such service interruptions, if frequent enough, would assume serious proportions from a service standpoint. It is, therefore, important that the apparatus of an exchange be regularly tested to determine, prior to its reported failure, if it is in suitable condition for rendering efficient service, or, after the apparatus has

50 been withdrawn from service for repair or

adjustment to determine if the repairs or adjustments which have been made, place the particular apparatus in serviceable condition. After the apparatus has been repaired or adjusted, it should be given vigorous and repeated tests under conditions simulating those under which it will function in actual service before it is again placed in service.

It is, therefore, the object of this invention to provide a testing device for enabling tests to be made of the individual selector switches of a telephone exchange system.

More particularly, it is the object of this invention to provide a testing device for testing distant district selectors of the type disclosed in the Patent No. 1,439,735 to Edmund W. Hancock, issued December 26, 1922, and office and final selectors of the type disclosed in the application of Walter P. Albert No. 470,767, filed May 19, 1921.

While the invention has been disclosed as particularly adapted for testing switches of the panel type as disclosed in the aforesaid applications, it will be, however, apparent from the following description that the invention has a wider utility and that by slight modification it could be adapted for testing other types of selector switches.

A feature of the invention is the provision of means for operating switches employed in the several selection stages of a mechanical switching system in simulation of the manner in which such switches function in actual service and for observing, through the medium of suitable supervisory apparatus, the accuracy with which the switches under test function.

A further feature of the invention relates to the provision of means for operating a selector switch in the establishment of all of the different classes of connections for which such switch is designed.

A further feature of the invention relates to the provision of means for adjusting a final selector switch for its ability to accurately function in testing lines of a private branch exchange group.

A further feature of the invention relates to the provision of means for conducting adjustment tests of various relays associated with selector switch circuits.

These and other features of the invention will be apparent from the following description taken in connection with the accom-

panying drawings in which Figs. 1, 2 and 3 show selector switches of the different selection stages of a mechanical exchange system upon which tests are to be conducted and 5 Figs. 4, 5 and 6, taken together, disclose the circuits of a portable selector-switch testing device. The drawings should be arranged for consideration with Figs. 1, 2 and 3 placed in the order named from left to right, Figs. 10 5 and 6 placed beneath Figs. 1 and 2, respectively, and Fig. 4 placed at the left of Fig. 5.

Fig. 1 shows the end of a trunk incoming to the exchange office terminating in a district selector switch and an auxiliary switch 15 individual to the district selector for associating an idle office sender therewith. An office sender is diagrammatically illustrated by the small rectangle in the lower right 20 corner of the figure designated "Sender." The incoming end of the trunk is provided with a make-busy jack which appears in the lower left corner of Fig. 2.

Fig. 2 shows an office selector which may 25 be selected by the district selector of Fig. 1 and which has access to trunk lines leading to outlying offices and directly to local final 30 selectors, one of which is disclosed in Fig. 3. In the lower portion of Fig. 2 jacks associated with the testing device of Figs. 4, 5 and 6 and make-busy jacks associated with the selector switches of Figs. 1, 2 and 3 together with patching cords for interconnecting them, are disclosed.

Fig. 3 shows a local final selector which 35 has access to lines of a special character such as tie lines to local operators' positions and test lines. In the lower portion of this 40 figure, mechanism common to a group of final selectors is illustrated, which functions to satisfy office senders with respect to incoming brush and group selections when the 45 final switch is seized directly by the office selector of Fig. 2, without the interposition of an incoming selector.

Fig. 4 shows the keyboard of a selector switch testing device.

Fig. 5 shows the counting relays of the testing device and the auxiliary switch 50 which functions to transmit relay call indicator code impulses when tests of the office selector of Fig. 2 are being conducted with relation to trunks extending to manual offices.

Fig. 6 shows controlling keys and supervisory apparatus of the testing device together with an auxiliary switch for carrying tests through their various stages.

Description of apparatus.

60 The automatic selector switches shown in Figs. 1, 2 and 3 are of the well-known power driven type in which a plurality of sets of brushes are mounted on a vertical brush shaft arranged to be selectively tripped into

engagement with their individual sections of the panel terminal bank. The brush shafts are propelled in a vertical direction by means of constantly rotating power drums. In general construction and operation 70 these switches are all of the same character as the one shown and described in detail in the patent to E. B. Craft and J. N. Reynolds No. 1,123,696, issued January 5, 1915. More specifically the district selector 75 150 shown in Fig. 1 is described in the patent to Edmund W. Hancock, No. 1,439,735 hereinbefore referred to, and the office and final selector's 250 and 350, of Figs. 2 and 3 are described in the application of Walter 80 P. Albert, Serial No. 470,767 hereinbefore referred to.

The auxiliary switches 100, 110, 210, 310, 320, 510 and 610 are of the sequence switch type substantially similar in principle and construction to the one described in the patent to J. N. Reynolds and C. F. Baldwin, No. 1,127,808, issued February 9, 1915. As regards switches 210 and 610, each of which appears on a separate sheet of the drawings, 90 it may be noted that all cam contacts located on the same sheet with one of these switches are controlled thereby. In Fig. 1 switch 110 controls all cam contacts located within the dotted square, the remaining cam contacts of the figure being controlled by switch 100. In Fig. 3 switch 320 controls only the cam contacts located within the lower portion of the figure enclosed by the dotted lines, the remaining cam contacts being 95 controlled by switch 310. In Fig. 5 cams 511, 512, 514 and 515 are controlled by switch 610 of Fig. 6, the remaining cams of the figure enclosed within the dotted lines being 100 controlled by switch 510. 105

The testing device disclosed in Figs. 4, 5 and 6 is enclosed in a portable box mounted upon rubber tired wheels for enabling it to be easily moved among the selector switch frames in the switching room of the office and is provided with suitable jacks, two of which are shown at 243 and 247 in Fig. 2 for connection, respectively, by patching cords to the make-busy jacks of the various selector switches of the office and to the jacks of test lines. Other jacks shown in various portions of Fig. 6 are also provided on the portable box for purposes which will be explained hereinafter. 110 In actual practice power is transmitted to the testing device through jacks on the testing device which are patched by cord circuits to suitable power jacks on the selector switch frames. Such power connections include current supply for the direct current motor 508 which drives the sequence switches 510 and 610, sources of 24-volt and 48-volt current for operating the various relays of the testing device and ground potential. For convenience of illustration, 115 120 125 130

however, these jacks have been omitted and the sources of current and ground potential have been shown directly associated with the different pieces of apparatus in 5 Figs. 4 to 6, inclusive.

The keyboard of Fig. 4 comprises a plurality of rows of keys upon which the test man may record office and numerical designations of numbers with which it is desired to test the various switches of the 10 exchange office. The keys of each row are locked when depressed under the control of the respective release magnets disclosed at the top of the figure.

15 The testing device is arranged to test three classes of switches as previously indicated, namely, district, office and final selectors, by three different methods at the 20 option of the test man. According to the first method which will hereinafter be termed the "step-by-step method", key 611 is operated whereupon the test progresses only from one stage to another under the 25 direct control of the test man through the repeated operation of the start key 607. Under this method the test man is enabled to closely observe the functioning of the selector under test. The second testing method may be termed the "continuous 30 method" as following the initial operation of the start key 607, the testing device proceeds through one complete cycle performing the various tests required of the 35 switch being tested and then automatically stops. Should a fault occur in the selector under test, the test is arrested immediately and an indication is given of the particular 40 stage in the test at which the fault occurred. The third testing method will be referred to hereinafter as the "exercise 45 method". For this type of test the exercise key 627 is depressed and thereafter the testing device functions in the same manner as under the continuous method except that the test continues through any number of 50 complete cycles until either stopped by a fault in the selector under test or by the restoration of the exercise key 627.

The testing device may be used for making 55 the following tests by any of the three methods outlined above:

1. Testing office and final selector switches together.
2. Testing the office selectors in conjunction 60 with full mechanical trunks with the key 628 operated.
3. Testing office selectors in conjunction 65 with relay call indicator trunks with the key 621 operated.
4. Testing final selectors only with key 623 operated.
5. Testing distant district selectors with key 612 operated.

Having now described in a general way 65 the apparatus employed in conducting tests

and the manner in which it is to be used, it is thought that the invention will be better understood from a consideration of the specific manner in which it functions. The testing device will, therefore, be first considered in connection with its operation in the conduct of a test on an office selector in conjunction with a final selector by the step-by-step method. 70

Testing an office selector in conjunction with 75 a final selector step-by-step method.

The test man before proceeding with the first test connects jack 243 of the testing device by patching cord 242 to the jack 238 80 which is connected to final multiples in the final selector switch 350, and connects jack 247 of the testing device by patching cord 248 with the make busy jack 249 of the office selector 250. If the office selector is busy, a 85 circuit is thereupon established from ground on conductor 241, from multiple 125 of a district selector which has seized the office selector, or from ground at cam 206 (2 to 7), over sleeve of jack 249, sleeve strand of 90 cord 248, sleeve of jack 247, right contact of cam 600 (1), relay 601, upper left contact of cam 602 (1) and to battery through the high resistance element. Relay 601 energizes in this circuit and closes a circuit for 95 the busy lamp 603 which may be traced from battery through lamp 603, the upper right contact of cam 604 (1), the upper left contact of said cam (1 to 15 $\frac{1}{4}$), the armature and front contact of relay 601, conductor 100 605, outer right armature and back contact of relay 606 to ground. With relay 601 energized the test circuit may not be advanced by the operation of start key 607, since the circuit from the start key 607 105 through the start relay 608 is opened at the armature and back contact of relay 601. Assuming that the office selector being tested is idle, then relay 601 does not energize and the selector is made busy from ground 110 through low resistance element, the lower contact of cam 602 (1), the winding of relay 601, thence as traced to conductor 241 and the multiple test terminals of all distant district selectors which have access thereto. As 115 soon as sequence switch 610 of the testing device leaves position 1, busy ground potential is supplied to the sleeve conductor 241, over the lower contact of cam 600 (1 $\frac{1}{2}$ to 18) and the upper right contact of cam 609 (1 $\frac{1}{2}$ 120 to 18).

Assuming that a step-by-step test is to be made the "step-by-step" key 611 and the "office to final" key 630 are depressed and locked in their depressed positions. Start key 607 is then operated and immediately released. Upon the operation of key 607 a circuit is closed for start relay 608 as follows: battery, winding of relay 608, innermost right spring and normal contact of 125 130

- the "distant district" key 612, inner right armature and back contact of relay 613, conductor 614, contact of key 607, left contacts of cam 615 (1), armature and back contact 5 of relay 601, conductor 605 to ground at the outer right armature and back contact of relay 606. Relay 608 energizes in this circuit and closes a shunt around the winding of relay 617 extending through the armature 10 and front contact of relay 608 to ground at the upper right contact of cam 616 (17 to 1). When the start key 607 is released, relay 617 energizes in series with relay 608 and closes a circuit for advancing sequence 15 switch 610 out of position 1 into position 2, this circuit extending from battery through the magnet winding of switch 610, the lower right contact of cam 618 (17 to 1) to ground at the armature and contact of 20 relay 617. As soon as the sequence switch leaves position 1 the holding circuit of relays 608 and 617 is opened at cam 616 and these relays thereupon release. As the sequence switch enters position 1 $\frac{1}{4}$ a circuit is closed 25 for relays 619 and 631 in series, which may be traced from battery through the windings of relays 631 and 619, the left contacts of cam 600 to ground at the upper right contact of cam 609 (1 $\frac{1}{2}$ to 18).
- 30 With sequence switch 610 in position 2 a circuit is closed for the office brush progress lamp 626 extending from battery through this lamp to ground at the upper left contact of cam 609 (2 to 3). A fundamental circuit 35 is also established between the testing device and the office selector 250 which may be traced as follows: from ground at cam 202 (1 to 4), conductor 240, ring of jack 249, ring strand of cord circuit 248, ring of jack 247, conductor 252, resistance 632, upper right contact of cam 620 (2 to 4), innermost left spring and normal contact of key 621, conductor 505, resistance 506 and the right winding of overflow relay 501 in parallel, 40 windings of stepping relay 500, armature and back contact of the No. 0' counting relay 503, conductor 507, upper contacts of cam 622, left spring and normal contact of key 623, inner right spring and normal contact 45 of key 621, lower right contact of cam 624 (2 to 4), resistance 633, conductor 625, normal contact of key ADJ, conductor 253, tip of jack 247, tip strand of cord circuit 248, tip of jack 249, conductor 239, upper left 50 contact of cam 201 (1 to 4), lower left contact of cam 203 (1) to battery through the right winding of control relay 200. Relays 200 and 500 energize in this circuit, but overflow relay 501 does not receive sufficient current to cause its energization at this time. Relay 200, upon energizing, closes a circuit 55 extending from ground at its left armature and front contact, over the lower left contact of cam 207 (1) and through the magnet winding of sequence switch 210 to battery

for driving the sequence switch out of position 1 into position 2. With relay 200 energized and sequence switch 210 in position 2, relay 200 is maintained energized over the fundamental circuit through its right armatures and front contacts and the lower right contact of cam 203 (1 to 4), the initial energizing circuit of relay 200 being opened at the lower left contact of cam 203 when the sequence switch leaves position 1. 70

Upon the closure of the fundamental circuit stepping relay 500 is operated and, as it will be assumed, that this test is being conducted with the No. 0 office brush key 400 and the No. 1 office group key 401 depressed, a circuit is established for the No. 0 counting relay 502. This circuit may be traced from battery through the lower contact of cam 511 (2), through the winding of relay 502, the No. 0 lead 513, the No. 0 lead 403 Fig. 4, left contact of key 400, conductor 404, upper left contact of cam 514 (2), conductor 516 and to ground through the armature and contact of stepping relay 500. Relay 502 energizes and locks in series 90 with the No. 0' counting relay 503, over a circuit from battery at the lower contact of cam 511, windings of relays 502 and 503 to ground at the armature and contact of relay 502. Relay 503 does not, however, energize at this time since its winding is shunted at the contact and armature of stepping relay 500. 95

At the office selector 250, with control relay 200 energized and sequence switch 210 100 in position 2, a circuit is established for the updrive magnet 211 which may be traced from battery through the winding of magnet 211, right contacts of cam 208 (2), to ground at the left armature and front contact of relay 200. Magnet 211, upon energizing, presses the depending portion of the switch shaft 214 against the constantly rotating updrive drum 236 whereby the switch shaft and attached brush sets are driven 105 upwardly in a brush selection movement. As the shaft approaches its first brush selection position, the shaft wiper 218 engages a conducting portion of commutator 221 thereby closing a circuit in shunt of the 110 stepping relay 500 which may be traced from battery, through the right winding of relay 200, right armatures and front contacts of said relay, right contacts of cam 203, commutator 221 to ground at wiper 218. Upon the establishment of this shunt, stepping relay 500 deenergizes, but control relay 200 remains energized. Upon the deenergization of relay 500 the shunt around the winding of relay 503 is opened and this relay energizes in the locking circuit of relay 502 and opens the fundamental circuit previously traced at its armature and contact, whereupon, relay 200 deenergizes. 120

As soon following the opening of the 130

fundamental circuit as the shaft wiper 218 engages the next insulating portion of commutator 221, the holding circuit of relay 200 is opened and this relay deenergizes, opening 5 the previously traced circuit of the up-drive magnet 211, thereby arresting the upward movement of the switch shaft. At its left armature and back contact, relay 200 establishes a circuit over the lower right 10 contact of cam 207 (2) and through the magnet winding of sequence switch 210 to battery, for driving the sequence switch out of position 2 into position 3. At the time the No. 0' counting relay 503 operated, relay 15 504 energized in parallel therewith and established a circuit from ground at its armature and contact, upper left contact of cam 649 (2), to battery through the magnet winding of sequence switch 610, for driving 20 this sequence switch out of position 2 into position 3. As the sequence switch 610 leaves position 2 the locking circuit of counting relays 502 and 503 is opened at the lower contact of cam 511 and relays 502, 25 503 and 504 release.

With sequence switch 610 in position 3 the test man again operates the start key 607 closing a circuit for the start relay 608 which may be traced from battery through 30 the winding of relay 608, the innermost right spring and normal contact of key 612, inner right armature and back contact of relay 613, conductor 614, contact of key 607 to ground at the upper right contact of cam 35 650 (3). Relay 608 energizes in this circuit and locks in series with relay 617 as previously described. Relay 617 energizes as soon as key 607 is released and closes a circuit over the lower right contact of cam 40 618 (3) for advancing sequence switch 610 into position 4. As the sequence switch 610 leaves position 3 the circuit of the office brush progress lamp 626 is opened at the upper left contact of cam 609 and when the 45 sequence switch reaches position 4 a circuit is established for the office group progress lamp 651 which may be traced from battery through lamp 651 to ground at the lower right contact of cam 609 (4 to 5). 50 With sequence switch 610 in position 4 a circuit is also closed from battery through the left winding of overflow relay 501 to ground at the lower left contact of cam 616 (4 to 14), but due to the inclusion of resistance in this circuit, relay 501 does not become energized.

The fundamental circuit previously traced through the windings of stepping relay 500, the right winding of overflow relay 501 and 55 the winding of control relay 200 of the office selector is again established, relays 200 and 500 becoming energized, but overflow relay 501 remaining unoperated, since current flowing through its right winding is in opposition to the current flowing through its

left winding. Relay 200, upon energizing over the fundamental circuit, closes a circuit from ground at its left armature and front contact, over the lower left contact of cam 207 (3) for advancing 70 sequence switch 210 into position 4. After the sequence switch 210 leaves position 3 relay 200 is maintained energized over the fundamental circuit through its right armatures and front contacts and the 75 lower right contact of cam 203 (1 to 4). With relay 200 energized and sequence switch 210 in position 4 the circuit of the updrive magnet 211 is again established and the switch shaft is again driven upwardly. 80 During the first portion of its upward movement the first set of brushes is tripped in the well-known manner through the operation of tripping magnet 213 which was energized over the lower contact of cam 206 (3 to 7) as soon as sequence switch 210 reached position 3. As the switch shaft continues in its upward movement the tripped set of brushes is moved adjacent the first group of terminals in the terminal bank 85 and a circuit is closed in shunt of the winding of stepping relay 500 which may be traced from battery, winding of relay 200, right armatures and front contacts of relay 200, the lower right and upper left contacts 90 of cam 203, commutator 222 to ground at shaft wiper 218. Relay 500 thereupon deenergizes, relay 200, however, remaining energized over the above traced shunt path.

At the testing device upon the energization of relay 500, with sequence switch 610 in position 4, a circuit is established for the No. 1 counting relay 517 extending from battery, through the upper right contact of cam 512 (4), winding of the No. 1 counting 100 relay 517, armature and back contact of the No. 1' counting relay 518, lead 519, lead 402 Fig. 4, alternate contacts of key 401, conductor 405, upper right contact of cam 514 (4), conductor 516 to ground through the armature and contact of stepping relay 500. Relay 517, upon energizing, locks in series with relay 518 to ground at the armature and contact of relay 517, but relay 518 does not energize until relay 500 deenergizes upon 105 the initial establishment of the shunt about its winding at commutator 222 of the office selector. Upon the first deenergization of relay 500, relay 518 energizes extending the lead 519 through the armature and front contact of relay 518 through the winding of the No. 0 relay 502 to battery at the lower contact of cam 511 (4). As the switch shaft 110 214 of the office selector 250 continues in its group selection movement, the shaft wiper 218 engages the next insulating portion of commutator 222 thereby opening the shunt around relay 500 again permitting its energization. The circuit for the No. 0 counting relay 502 is now completed at the armature 115 120 125 130

- ture and contact of relay 500 and relay 502 thereupon locks in a circuit extending through the winding of relay 503. As the brush shaft 214 continues its movement, 5 shaft wiper 218 engages the next conducting portion of commutator 222 and relay 500 again deenergizes. Relays 503 and 504 now energize in the locking circuit of relay 502, relay 503 opening the fundamental circuit, 10 and relay 504 closing the previously traced circuit for advancing sequence switch 610 out of position 4 into position 5. When sequence switch 610 leaves position 4 the locking circuits of the energized counting relays 15 are opened and such relays release, and the circuit previously traced through the windings of relays 619 and 631 is also opened at the upper left contact of cam 600. Relay 619, upon deenergizing, places shunts around 20 the resistance elements 632 and 633 which have up to this time been included in the fundamental circuit hereinbefore traced.
- At the office selector as soon following the opening of the fundamental circuit as the 25 wiper 218 engages the next insulating portion of commutator 222, relay 200 deenergizes opening the circuit of the updrive magnet 211 and closing a circuit over its left armature and back contact and the lower 30 right contact of cam 207 (4) for advancing sequence switch 210 into position 5. With sequence switch 210 in position 5 a circuit is established from battery through the left winding of relay 200 to ground, through the 35 left contacts of cam 209. Relay 200, upon energizing in this circuit, establishes a circuit over its left armature and front contact for driving sequence switch 210 out of position 5 into position 6. When sequence 40 switch 210 leaves position 5 the circuit just traced for relay 200 is opened at contacts of cam 209 and, as it will be assumed that the first trunk of the group upon which the brushes of the selector are standing is idle, 45 there is no locking circuit for relay 200 over test brush 217 and the upper contacts of cam 205. Relay 200, therefore, deenergizes as soon as sequence switch 210 leaves position 5 without causing the advance of the 50 switch shaft 214 in its hunting movement, and at its left armature and back contact closes the circuit for advancing sequence switch 210 into position 7. In position 7 relay 200 again energizes over its left winding and the left contacts of cam 209 causing the advance of sequence switch 210 into the talking position 8. Relay 200 now establishes a locking circuit for itself extending from battery through its right winding 55 right armatures and front contacts, the left contacts of cam 205, conductor 241, sleeve of jack 249, sleeve strand of cord circuit 248, sleeve of jack 247, the lower contact of cam 600 (1½ to 18) to ground, at the upper right 60 contact of cam 609 (1½ to 18) and is thus maintained energized until the test of selectors 250 and 350 is completed. The final trunk selected by switch 250 is maintained busy by ground potential connected to the multiples of terminal 229, over brush 217 70 and the right contact of cam 206.
- With the sequence switch 610 of the testing device in position 5 and the office selector sequence switch 210 in position 8, a circuit is established for relay 652 which may 75 be traced from battery, through the winding of control relay 300 of the final selector, the left contacts of cam 316, the upper left contact of cam 306 (1 to 19), the lower right contact of cam 305 (1 to 15), resistance 80 330, conductor 232, bank terminal 227 and brush 215 of office selector 250, the upper contacts of cam 201 (8), conductor 239, tip of jack 249, tip strand of cord circuit 248, tip of jack 247, conductor 253, normal contact of key ADJ, conductor 625, intermediate armature and back contact of relay 619, lower left contact of cam 624 (5), 16,000 ohm resistances 680 and 676 winding of relay 652, upper left contact of cam 620 (5 to 90 6), the lower armature and back contact of relay 619, conductor 252, ring of jack 247, ring strand of cord circuit 248, ring of jack 249, conductor 240, upper contacts of cam 204 (8), brush 216 and bank terminal 228 95 of office selector 250, conductor 233, resistance 332 to ground at the upper contacts of cam 317. Relay 652 receives sufficient current in this circuit to operate if the trunk is found to be in proper condition, but due 100 to the inclusion of the 16,000 ohm resistances at the testing device, the control relay 300 of the final selector does not operate. Relay 652, upon energizing, closes an obvious circuit for relay 637 which at its right armature and front contact establishes a circuit over the upper right contact of cam 653 (5) and through the magnet winding of sequence switch 610 to battery for driving the sequence switch into position 6. As soon as 105 the sequence switch 610 leaves position 5 the circuit of the office group progress lamp 651 is opened at the lower right contact of cam 609 (4 to 5) indicating that office group selection has been successfully completed, and 110 at the lower left contact of cam 624 opens the circuit of relay 652, which in turn, opens the circuit of relay 637. With sequence switch 610 in position 6, the circuit of the incoming brush progress lamp 654 is closed 115 over the lower left contact of cam 609 (6 to 7). As no incoming selectors are employed, the incoming brush and group selections are taken care of in the final selector 350. The incoming selections being always No. 0 120 brush and No. 0 group.
- With sequence switch 610 in position 6, a fundamental circuit is now established through the windings of stepping relay 500 and the winding of control relay 300 of the 125 130

final selector, which may be traced from battery through the winding of relay 300, thence as previously traced to conductor 625, the intermediate armature and back contact of relay 619, the lower right contact of cam 624 (6 to 14), the inner right spring and normal contact of key 621, the left spring and normal contact of key 623, the upper contacts of cam 622, conductor 507, the armature and back contact of the No. 0' counting relay 503, the windings of stepping relay 500, resistance 506 and the right winding of overflow relay 501 in parallel, conductor 505, the inner left spring and normal contact of key 621, the upper right contact of cam 620, the lower armature and back contact of relay 619, conductor 252, thence as previously traced to ground at the upper contacts of cam 317. Relays 300 and 500 energize in this circuit, relay 500 closing a circuit for the No. 0 counting relay 502 which may be traced from battery through the lower contact of cam 511 (6), winding of counting relay 502, lead 513, the No. 0 lead at the innermost left spring and normal contact of key 628, conductor 520, lower left contact of cam 514 (6), conductor 516 to ground at the armature and contact of relay 500. Relay 502 locks in series with relay 503 but the latter relay being shunted at the armature and contact of stepping relay 500 does not energize at this time.

At the final selector 350 upon the energization of relay 300 a circuit is established from ground at the right armature and front contact of this relay, over the upper right contact of cam 312 (1) and to battery through the magnet winding of sequence switch 310 for advancing this sequence switch out of position 1 into position 2. After sequence switch 310 leaves position 1 relay 300 maintains itself locked to the fundamental circuit over its left armature and front contact. Immediately that sequence switch 310 reaches position 1 $\frac{1}{2}$ on its way to position 2 a circuit is closed from battery through the winding of sequence switch magnet 320, contact of cam 321 (1), lower left contact of cam 311 (1 to 4), lower right contact of said cam (1 $\frac{1}{2}$ to 14) to ground. Sequence switch 320 which is common to all final selector switches, energizes and rotates through a complete cycle for the purpose of sending impulses back to the testing device to satisfy any registrations which have been recorded on the keyboard thereof and which normally serve to control incoming brush and incoming group selections. During the rotation of switch 320 from position 1 through its complete cycle into position 1 again, the upper right contact of cam 354 is closed in the successive positions 2 to 18. At each of these closures the following circuit is momentarily established from battery, winding and front contact and left armature of relay 300, upper left contact of cam 306 (1 to 10), lower right contact of cam 305 (1 to 15), resistance 330, contact of cam 308 (1 $\frac{1}{2}$ to 2) to ground through cam 354. This circuit maintains the energization of control relay 300 but shunts down stepping relay 500 of the testing device. Since as herein assumed the No. 0 counting relay 502 was energized by the energization of relay 500, the first deenergization of relay 500 upon the first closure of cam contact 354 in position 2 will permit the energization of relays 503 and 504 in series with relay 502. Relay 503 now opens the fundamental circuit causing the release of relays 300 and 500, and relay 504 closes the previously traced circuit for advancing sequence switch 610 of the testing device out of position 6 into position 7. Sequence switch 610 upon leaving position 6 opens the holding circuit of relays 502, 503 and 504 which thereupon release. Relay 300 of the final selector, upon deenergizing, closes a circuit which extends from battery through the winding of sequence switch magnet 310, upper left contact of cam 312 (2), the right armature and back contact of relay 300, to ground for driving sequence switch 310 into position 3. With sequence switch 610 in position 7, the test man again operates the start key 607 whereupon start relays 608 and 617 function over the circuit previously traced for driving sequence switch 610 out of position 7 into position 8. When sequence switch 610 leaves position 7 the circuit of the incoming brush progress lamp 654 is opened at the lower left contact of cam 609 (6 to 7), indicating that no fault has occurred in making incoming brush selection, and the holding circuit of relays 608 and 617 is opened at the upper right contact of cam 616 (7). When switch 610 reaches position 8 the circuit of in coming group progress lamp 655 is closed over the upper left contact of cam 659 (8 to 9). With the sequence switch 610 in position 8 and sequence switch 310 of the final selector in position 3, the fundamental circuit previously traced through the windings of relays 500 and 300 is again established, relay 500 again closing the circuit of the No. 0 counting relay 502 from battery, lower contact of cam 511 (8), winding of relay 502, lead 513, No. 0 lead at the innermost right spring and normal contact of key 628, conductor 521, the lower right contact of cam 514 (8), conductor 516 to ground at the armature and contact of relay 500. Relay 502, upon energizing, locks in series with relays 503 and 504, but the latter relays do not energize at this time since they are shunted at the armature and contact of relay 500.

At the final selector upon the energization of relay 300, the previously traced circuit is closed for advancing sequence switch 130

310 out of position 3 into position 4. After sequence switch 310 leaves position 3, relay 300 maintains itself connected to the fundamental circuit over its left armature and front contact. If at this time sequence switch 320 has not completed its first cycle, the remaining positions of this switch will be utilized in sending back impulses to the testing device to satisfy the registration 10 thereof which normally controls incoming group selection. On the other hand, if the sequence switch 320 has already reached its normal position, or if it reaches the end of its first cycle prior to the time the proper 15 number of impulses have been reverted to the testing device, it will be driven through a second cycle by means of the circuit previously traced through the contact of sequence switch cam 321 and the lower contacts of cam 311. With sequence switch 310 in position 4 successive closures of sequence switch cam 354 momentarily complete the following circuit for relay 300 in shunt of the windings of relay 500: battery, winding 20 and front contact and left armature of relay 300, upper left contact of cam 306 (1 to 10), the lower right contact of cam 305 (1 to 15), resistance 330, contact of cam 308 (3 $\frac{3}{4}$ to 4), thence through the upper right contact of 25 cam 354 to ground. Upon the first closure of cam 354 following the energization of relay 300 for controlling incoming group selection, since the No. 0 counting relay 502 is at the time energized, relay 500 will 30 release and permit the energization of relays 503 and 504. Relay 503, upon energizing, opens the fundamental circuit and relay 504 closes the previously traced circuit for advancing sequence switch 610 out of position 35 8 into position 9. Sequence switch 610, upon leaving position 8, opens the locking circuit of relays 502, 503 and 504 whereupon they release. Relay 300 of the final selector, upon releasing, closes a circuit over its right armature and back contact and the upper left contact of cam 312 (4) for driving sequence switch 310 out of position 4 into position 5. When following this the sequence switch 320 reaches position 1, it comes to rest in as 40 much as its operating circuit is now open at the lower left contact of cam 311 (1 to 4). With sequence switch 610 in position 9 the test man again operates the start key 607 whereupon relays 608 and 617 function as 45 before described for driving sequence switch 610 out of position 9 into position 10. When sequence switch 610 leaves position 9 the circuit of incoming group progress lamp 655 is opened, and when the switch reaches position 10 a circuit is closed over the upper right contact of cam 659 (10 to 11) for the final brush progress lamp 656. The extinguishing of lamp 655 indicates that no fault 50 has occurred in making incoming group selection.

With sequence switch 610 in position 10 and sequence switch 310 of the final selector 350 in position 5, the previously traced fundamental circuit through the windings of relay 500 and the winding of relay 300 is again established, relays 300 and 500 becoming energized. It will now be assumed that to select the test line 344, 345, 346, appearing in the bank of selector 350 on terminals No. 97 in the first brush group, the test man has depressed the No. 0 hundreds key 406, the No. 9 tens key 407 and the No. 7 units key 408. Relay 500, upon energizing, establishes a circuit from battery, the lower contact of cam 511 (10), the winding of counting relay 502, the No. 0 lead 513, the No. 0 lead 409 Fig. 4, the right contact of key 406, conductor 410, lower left contact of cam 515 (10), conductor 516 to ground at the armature and contact of relay 500. The relay 502 energizes in this circuit locking through the winding of relays 503 and 504 in parallel. Relays 503 and 504 do not energize at this time, however, since they are shunted at the armature and contact of relay 500. At the final selector upon the energization of relay 300 over the fundamental circuit, relay 300 closes a holding circuit for itself over its left armature and front contact and establishes a circuit from battery, winding of sequence switch magnet 310, upper right contact of cam 312 (5), front contact and right armature of relay 300 to ground, driving sequence switch 310 out of position 5 into position 6. In position 6 a circuit is closed for the high speed updrive magnet 333 traceable from battery through the winding of said magnet, right contact of cam 319 (6), upper left contact of cam 315 (5 $\frac{3}{4}$ to 6), front contact and right armature of relay 300 to ground. Magnet 333, upon energizing, presses the depending portion of switch shaft 337 against the updrive drum 361 whereupon the switch shaft is driven upwardly to select the proper set of brushes. As the switch shaft reaches its first brush selection position, a circuit is closed in shunt of the windings of stepping relay 500 from battery, winding, left armature and front contact of relay 300, upper left contact of cam 306 (1 to 10), upper right contact of cam 305 (5 $\frac{3}{4}$ to 6), commutator 360, brush 348 to ground. This circuit holds relay 300 energized and causes the deenergization of relay 500, which by removing the shunt from relay 503 permits the energization of relay 503 in series with relay 502. Relay 504 now energizes in parallel with relay 503.

Relay 503, upon energizing, opens the fundamental circuit through the windings of relays 500 and 300 and relay 504 closes the previously traced circuit extending over the upper left contact of cam 649 for driving sequence switch 610 out of position 10 into position 11. Sequence switch 610, upon

leaving position 10, opens the locking circuit of relays 502, 503 and 504. As soon following the opening of the fundamental circuit as the shaft wiper 348 engages the next insulating portion of commutator 360, the control relay 300 becomes deenergized and opens the circuit of the updrive magnet 333. Relay 300 also completes a circuit from battery through the winding of sequence switch magnet 310, the upper left contact of cam 312 (6), back contact and right armature of relay 300 to ground for driving sequence switch 310 into position 7. In this position a circuit is established from battery, through the winding of trip magnet 336, the lower right contact of cam 318 (7 to 8), upper right contact of said cam (1 to 15) to ground. Magnet 336 now operates and prepares for tripping the selected set of brushes at the next upward movement of the switch shaft 337.

With sequence switch 610 in position 11 the test man again operates the start key 607, whereupon relays 608 and 617 function as before described for driving sequence switch 610 out of position 11 and into position 12. When sequence switch 610 leaves position 11 the holding circuit of relays 608 and 617 is opened and the circuit previously traced for the final brush progress lamp 656 is also opened indicating that no fault has occurred in making final brush selection. When sequence switch 610 reaches position 12 the circuit for the final tens progress lamp 657 is established from battery through lamp 657 to ground at the lower right contact of cam 659 (12 to 13).

With sequence switch 610 in position 12 and sequence switch 310 of the final selector 350 in position 7, the fundamental circuit previously traced is again established and relays 300 and 500 operate. Relay 500 upon operating now closes a circuit for the No. 9 counting relay 522, it having been assumed that the No. 9 tens key 407 was depressed. This circuit is as follows: battery, lower contact of cam 511 (12), the No. 9 relay 522, armature and back contact of No. 9' counting relay 523, lead 524, lead 411 Fig. 4, the left contact of key 407, conductor 412, right contact of cam 515 (12), conductor 516 to ground at the armature and contact of relay 500. Relay 522 energizes in this circuit and locks in series with relay 523. Relay 523 being shunted at the armature and contact of relay 500 does not energize at this time.

At the final selector upon the energization of relay 300 over the fundamental circuit, the relay 300 closes a holding circuit for itself and also completes a circuit from battery through the winding of sequence switch magnet 310, upper right contact of cam 312 (7), front contact and right armature of relay 300 to ground. Sequence switch 310 is now driven from position 7 into position 8 where a circuit is closed from battery through winding of high speed updrive magnet 333, right contact of cam 319 (8), upper left contact of cam 315 (7 $\frac{3}{4}$ to 8), front contact and right armature of relay 300 to ground. Magnet 333, upon energizing, presses the depending portion of switch shaft 337 against the drum 361, whereupon the switch shaft is driven upwardly and the selected set of brushes 338, 339 and 340 are tripped and moved over the terminals of the portion of the bank to which they are allotted. As the switch shaft moves upwardly and approaches each group selection position, the shaft wiper 347 engages a metallic portion of the commutator 352 and the following circuit is momentarily established in shunt of the stepping relay 500: battery, winding left armature and front contact of relay 300, upper left contact of cam 306 (1 to 10), lower right contact of cam 306 (7 $\frac{3}{4}$ to 8), commutator 352, wiper 347, to ground. This circuit holds relay 300 energized, but shunts down stepping relay 500, which permits the successive operation of counting relays beginning with the No. 9' counting relay 523 until the No. 0' counting relay 503 energizes, at which time the brush shaft will have positioned the brushes 338, 339 and 340 beneath the tenth group of bank terminals. Relay 503 upon energizing in parallel with relay 504, opens the fundamental circuit and relay 504 establishes the previously traced circuit over the upper left contact of cam 649 (12) for advancing sequence switch 610 into position 13. Sequence switch 610 upon leaving position 12 opens the locking circuits of all operated counting relays at contacts of cams 511 and 512.

At the final selector switch and as soon following the opening of the fundamental circuit by the counting relay 503 as the shaft wiper 347 engages the next insulating portion of commutator 352, relay 300 becomes deenergized and opens the circuit of updrive magnet 333 causing the switch shaft to cease its upward movement. Relay 300 also establishes a circuit from battery through the winding of sequence switch magnet 310, upper left contact of cam 312 (8), back contact and right armature of relay 300 to ground, for advancing said sequence switch into position 9.

With sequence switch 610 of the testing device in position 13 the test man again operates the start key 607 whereupon relays 608 and 617 function as before described to advance sequence switch 610 into position 14. When sequence switch 610 leaves position 13 the holding circuit of relays 608 and 617 is opened and the circuit of the final tens progress lamp 657 is also opened at the lower right contact of cam 659. With sequence

switch 610 in position 14, the circuit of the final units progress lamp 658 is closed as follows: battery, lamp 658, conductor 660, outer left armature and back contact of relay 509, conductor 525 to ground at the lower left contact of cam 659 (14 to 15). The extinguishing of lamp 657 indicates to the test man that no fault has occurred in making final tens selection.

10 With sequence switch 610 in position 14 and sequence switch 300 of the final selector 350 in position 9, the fundamental circuit previously traced is again established and relays 300 and 500 operate. Relay 500, upon 15 operating, now closes a circuit for the No. 7 counting relay 526, it having been assumed that the No. 7 units key 408 was depressed. This circuit may be traced from battery, lower contact of cam 511 (14), winding of 20 relay 526, armature and back contact of relay 527, No. 7 lead 528, No. 7 lead 413 Fig. 4, left contact of key 408, conductor 414, upper contact of cam 515 (14), conductor 516 to ground at the armature and contact 25 of relay 500. Relay 526 energizes in this circuit and locks in series with relay 527. Relay 527, however, does not energize at this time as it is shunted at the armature and contact of relay 500.

30 At the final selector, relay 300 upon energizing over the fundamental circuit, closes a holding circuit for itself and completes a circuit from battery through the winding of sequence switch magnet 310, upper right 35 contact of cam 312 (9), front contact and right armature of relay 300 to ground, driving sequence switch 310 out of position 9 into position 10. In this position a circuit is closed from battery through the winding of the low speed updrive magnet 334, left contact of cam 319 (10), upper left contact of cam 315 (9 $\frac{1}{4}$ to 10), front contact and right armature of relay 300 to ground. Magnet 334, upon energizing, presses the depending portion of switch shaft 337 against the drum 362 whereupon the switch shaft is driven upwardly at a low rate of speed. As the switch shaft moves the selected brushes 338, 339 and 340 over each set of terminals 40 in the selected group, the shaft wiper 348 engages a conducting portion of the commutator 360, momentarily closing a shunt around the windings of stepping relay 500 which may be traced as follows: battery, winding left armature and front contact of relay 300, upper left contact of cam 306 (1 to 10), upper right contact of cam 305 (9 $\frac{1}{4}$ to 10), commutator 360 to ground at wiper 348. Relay 300 is maintained in this circuit, but relay 45 500 deenergizes each time the circuit is established whereupon the counting relays beginning with relay 527 are operated in succession until the No. 0' counting relay 503 operates in parallel with relay 504. Relay 503, upon operating, opens the fundamental

circuit and relay 504 closes the previously traced circuit for advancing sequence switch 610 out of position 14 into position 15. When sequence switch 610 leaves position 14 the holding circuits of the operated counting relays are opened at the contacts of cams 511 and 512.

With sequence switch 610 in position 15 a circuit is closed for lamp 661 which may be traced from battery through lamp 661, the inner right spring and normal contact of the make-busy key, the outer right armature and back contact of relay 640 to ground at the upper left contact of cam 650 (15). A circuit is also closed from battery through supervisory lamp 662, the armature and back contact of relay 663, the armature and back contact of relay 635 to ground through the lower contact of cam 616 (15 to 17). The lighting of these lamps at this time is an indication that selections have all been completed.

At the final selector following the completion of units selection, relay 300 deenergizes as soon following the opening of the fundamental circuit as the brushes 338, 339 and 340 are accurately centered on the terminals 341, 342 and 343, at which time, wiper 348 engages an insulating portion of commutator 360. Relay 300, upon deenergizing, opens the circuit of updrive magnet 334 causing the switch shaft to cease its upward movement and completes a circuit from battery through the winding of sequence switch magnet 310, upper left contact of cam 312 (10), back contact and right armature of relay 300 to ground for driving said sequence switch out of position 10 into position 11.

A test is now made to determine the busy or idle condition of test line 344, 345 and 346 upon which the brushes of the final selector switch have been set. Since the make-busy key of the testing device is in its normal position, the test line will test idle and the test circuit may, therefore, be traced from battery, right winding of relay 302, lower left and upper right contacts of cam 314 (11 to 13), left winding of relay 302, lower contact of cam 329 (11 to 16 $\frac{1}{2}$), brush 340, terminal 343, conductors 346 and 235, sleeve of jack 238, sleeve strand of cord circuit 242, sleeve of jack 243, inner left spring and normal contact of make-busy key, right contacts of cam 615 (2 to 18), winding of relay 601, upper right contact of cam 602 (2 to 18), resistance 664, to ground at the normal contact of key P. B. X. Due to the full ground potential on terminal 343, sufficient current flows through the windings of relay 302 to cause its energization. Relay 302, upon operating, closes a circuit from battery, through its left armature and front contact, left winding of said relay, lower contact of cam 329 (11 to 16 $\frac{1}{2}$), brush 340 to the test terminal 343 and also to the multiples thereof in other switches. The re-

sistance of this circuit through the left winding of relay 302 is low and therefore reduces the potential on the multiples of test terminal 343 to a point where relays 302 of 5 other switches cannot operate when a test is made thereby, making the test line non-selectable to other switches. Relay 302 also completes a circuit from ground through its right armature and front contact, lower left 10 contact of cam 312 (11), winding of sequence switch magnet 310 to battery for driving the sequence switch out of position 11 into position 13. In positions 12 and 13 a circuit is closed over the right winding of 15 relay 301 and contacts of cam 317, but relay 301 does not receive sufficient current to energize at this time. In position 13 a circuit is closed from battery through the winding of sequence switch magnet 310, upper left 20 contact of cam 312 (13), back contact and right armature of relay 300 to ground for driving sequence switch 310 into position 14. In position 14 relay 300 is energized by means of a circuit from battery through the 25 winding of said relay, lower left contact of cam 316 (1 to 14), upper left contact of cam 316 (14), upper right contact of cam 311 (14 to 18), lower right contact of said cam (14 to 14), to ground. Relay 300 completes 30 a circuit from battery through the winding of sequence switch magnet 310, upper right contact of cam 312 (14), front contact and right armature of relay 300 to ground, driving sequence switch 310 into position 15. On 35 leaving position 14 sequence switch 310 opens the left contacts of cam 316, but relay 300 remains actuated in a circuit from battery through the winding of said relay, its front contact and left armature, upper right 40 contact of cam 311 (14 to 18), upper left contact of said cam (2 to 18), conductor 254, contacts 245 associated with jack 244, conductor 234, terminal 229, brush 217 of office selector 250, upper right contact of 45 cam 206 (6¹₂ to 8¹₂) to ground. In position 15 of sequence switch 310 a circuit is closed from battery through the winding of sequence switch magnet 310, lower left contact of cam 312 (15), front contact and right 50 armature of relay 302 to ground for advancing sequence switch 310 into the talking position 16.

At the testing device if there was no fault in the sleeve circuit of the final selector, relay 601 energized in the circuit traced through the windings of the test relay 302, and upon energizing, established a circuit from battery through the winding of relay 640, lower right and upper left contacts of 55 cam 604, armature and front contact of relay 601, conductor 605 to ground at the outer right armature and back contact of relay 606. The operation of relay 640 now opens the circuit previously traced for sleeve lamp 661 and opens at its left armature and back 60

contact the operating circuit for relay 639.

At the final selector while its sequence switch 310 was still in the testing position 11, a circuit was also closed for operating 70 supervisory relays 634 and 663 of the testing device. If the circuit to operate these relays is closed prior to the circuit previously traced for relay 601, it may be traced as follows: battery, lower left and upper right 75 contacts of cam 309 (11 to 15), resistance 331, conductor 233, terminal 228 and brush 216 of office selector 250, the upper contacts of cam 204 (8), conductor 240, ring of jack 249, ring strand of cord 248, ring of jack 247, conductor 252, lower armature and back contact of relay 619, lower contact of cam 620 (15 to 17), lower left winding of repeating coil 668, lower winding of relay 634, lower armature and back contact of 80 relay 631, winding of polarized relay 663, intermediate armature and back contact of relay 631, upper winding of relay 634, upper left winding of repeating coil 668, upper contact of cam 624 (15), intermediate 85 armature and back contact of relay 619, conductor 625, normal contact of key ADJ, conductor 253, tip of jack 247, tip strand of cord 248, tip of jack 249, conductor 239, upper contacts of cam 201 90 (8), brush 215 and terminal 227 of office selector 250, conductor 232, resistance 330, lower right and upper left contacts of cam 305 (11 to 15) to ground. The direction 95 of current flowing in this circuit is such as 100 to operate both relay 634 and polarized relay 663. Relay 663, upon operating, now opens at its armature and back contact the circuit of supervisory lamp 662. Relay 634, upon operating, closes a circuit for relay 105 639, it being previously assumed that relays 601 and 640 have not yet operated. The circuit of relay 639 may be traced from battery, relay 639, left armature and back contact of relay 640 to ground at the armature 110 and front contact of relay 634. Relay 639, upon operating, locks through its right armature and front contact to ground at the lower right contact of cam 616 (15 to 17) and at its left armature and back contact 115 opens the circuit previously traced for lamp 665 preventing it from lighting when the relay 640 later operates.

When now the relay 640 operates in the manner previously described, sequence switch 610 is advanced out of position 15 into position 16 over a circuit from battery magnet winding of sequence switch 610, lower right contact of cam 653 (15), left armature and front contact of relay 639, conductor 677, to ground at the inner right armature and front contact of relay 640. With relay 640 operated the lamp 661 is extinguished as previously described, indicating no fault in the sleeve circuits of the final selector. 120 125 130

When the sequence switch 610 leaves position 15 the circuit previously traced for relays 634 and 663 is opened at cam 624 and these relays release, relighting the supervisory 5 lamp 662. The lighting of this lamp at this time is without function and may be disregarded by the test-man. As sequence switch 610 leaves position 15 the circuit of final units progress lamp 658 is open at the lower left contact of cam 659 (14 to 15), indicating that no fault has occurred in 10 making units selection. Should relays 601 and 640 fail to operate the sequence switch 610 will not advance and the lamp 661 will, 15 therefore, remain lighted and relays 634 and 663 will remain energized. When sequence switch 610 reaches position 16, relays 634 and 663 reoperate extinguishing lamp 662.

Should the circuits for operating relays 634 and 601 be closed simultaneously with sequence switch 310 of the final selector in position 11, the relay 634 will operate and close a circuit from ground at its armature 25 and front contact, the left armature and back contact of relay 640, to battery through the winding of relay 639 which then locks to ground at the lower right contact of cam 616 (15 to 17). Relay 640, which is energized upon the operation of relay 601, is slow to operate, while relay 639 is fast to operate, therefore, relay 639 has sufficient time to operate and lock before relay 640 operates and opens its circuit. With relay 30 639 operated, lamp 665 cannot light and sequence switch 610 is advanced to position 16 as soon as relay 640 operates, the circuits then functioning as above described. The relay 640 is made slow-to-operate to allow 35 for slight inaccuracies in the cutting of cams 309 and 317 of the final circuit.

Should the circuit to operate relay 601 be closed before the circuit to operate relay 634 is closed, relay 601 will operate relay 45 640, in turn preventing the operation of relay 639 when relay 634 later operates.

Since relay 640 is now energized and relay 639 is not operated, a circuit is closed for the lamp 665, through the left contacts 50 of cam 667, left armature and back contact of relay 639 to ground at the inner right armature and front contact of relay 640. The extinguishing of lamp 661 indicates that no fault exists on the sleeve circuit of the final selector. Under this condition the testing sequence switch 610 remains in position 15 as there is no circuit closed by relay 639 for driving it into position 16. If the lamp 665 remains lighted 55 at this time, it will indicate to the test-man trouble in the talking conductors of the final selector as will hereinafter be described.

If the sequence switch 610 remains in position 15 and lamp 665 remains lighted after 60 relays 601 and 640 have operated, it in-

dicates to the test-man that a fault has occurred at either or both of the cams 309 and 317 of the final circuit. If, however, with sequence switch 610 in position 15, cams 309 and 317 supply battery and ground potential 70 properly, relays 634 and 663 operate as above described and sequence switch 610 is advanced into position 16 where it awaits the closure of the talking circuit at the final selector. When the final selector finishes testing 75 and the sequence switch 310 thereof moves into the talking position 16, the circuit of relays 634 and 663 above traced is changed, conductor 232 in such circuit being disconnected from battery at the lower 80 contact of cam 309 and connected over the lower left contact of cam 305 (16 to 17), the lower left contact of cam 306 (16), brush 338, terminal 341, conductor 344, conductor 230, tip of jack 238, tip strand of cord 242, tip of jack 243 to ground at the left normal contacts of relay 645, and conductor 233 in the circuit of relays 634 and 663 is then disconnected from ground at the upper contact 85 of cam 317 and connected over the upper contact of cam 307 (16), brush 339, terminal 342, conductor 345, conductor 231, ring of jack 238, ring strand of cord 242, ring of jack 243, normal contacts of the right armature of relay 645 to battery through the 90 left winding of relay 643. Polarized relay 663 now releases as the current flowing through its winding is reversed and supervisory lamp 662 is now permitted to relight. Relays 634 and 643, however, are energized 95 in this circuit.

If an open circuit should occur in the final 100 at cams 305, 306 or 307, or at the brushes 338 and 339, or the tip side of the final circuit be grounded, or the tip and ring sides be short circuited, relay 634 will not remain 105 operated and upon its deenergization will close the circuit of lamp 666 from battery, through the lamp 666, the upper right and lower left contacts of cam 667 to ground at 110 the armature and back contact of relay 634, thereby indicating to the test-man either a short circuit, an open circuit, or a ground on the tip conductor of the final selector. Relay 643 which was included in the circuit 115 just traced and operated thereover, locks through its right winding and right armature and front contact to ground at the upper left contact of cam 669 and at its left armature and front contact closes an obvious circuit for relay 644. Relay 643 also closes at its right armature and front contact a circuit for lamp 670 which extends to ground at the upper left contact of cam 669 (1 to 16). If the final circuit was found to 120 be open, relay 643 would not have operated and lamp 670 would not, therefore, be lighted. With both lamps 666 and 670 lighted the test-man is apprised of the fact 125 that the trouble at the selector circuit is 130

either due to a short circuit or ground on the tip conductor.

The test-man now operates the answering key ANS which locks in its operated position and establishes a circuit for reversing relay 645 which may be traced from battery through the winding of relay 645, contact of key ANS to ground at the left armature and contact of relay 644. Relay 645 now reverses the connection of ground and battery through the left winding of relay 643 and the windings of relays 634 and 663, over the talking conductors of the office and final selector circuits and introduces a resistance 671 of two thousand ohms. Polarized relay 663 again operates in series with relays 634 and 643 and opens the circuit of supervisory lamp 662 and closes a circuit for relay 638. The circuit of relay 638 may be traced from battery, outer right armature and front contact of relay 644, winding of relay 638, armature and front contact of polarized relay 663, armature and back contact of relay 635 to ground at the lower right contact of cam 616 (15 to 17). Relay 638, upon operating, closes a circuit for the answering relay 646 from battery, winding of relay 646, armature and contact of relay 638 to ground at the lower right contact of cam 669 (16), relay 646 locking to ground at cam 669 through its inner left armature and front contact. If the final selector should be grounded on the ring side of its circuit, the polarized relay 663 will not operate as above described upon the operation of the answering key ANS when battery and ground connections are reversed by the operation of relay 645 and under this condition supervisory lamp 662 remains lighted indicating that the ring side of the final selector is grounded.

The test-man now operates the start key 607 which closes a circuit for the start relay 608 as follows: battery, relay 608, innermost right spring and normal contact of key 612, inner right armature and back contact of relay 613, conductor 614, key 607, inner right armature and front contact of relay 646 to ground. Relay 608, upon energizing, locks in series with relay 617 to ground at the upper right contact of cam 616 (16), and as soon as key 607 is released, relay 617 energizes, closing the previously traced circuit for advancing sequence switch 610 out of position 16 into position 17. As the sequence switch leaves position 16, relays 608, 617, 638, 643, 644, 645 and 646 release and the lamp 670 is extinguished. The release of relay 645 again reverses the battery and ground connections to the tip and ring conductors of the final selector circuit thereby causing the release of polarized relay 663, which upon releasing, again lights the lamp 662. Lamp 662 now serves as a disconnect signal.

With the sequence switch 610 of the testing device in position 17 and the lamp 662 lighted, the test-man operates the disconnect key 672 closing a circuit for relay 641 from battery, winding of relay 641, the contacts of key 672 to ground at the upper right contact of cam 609 (1½ to 18). Relay 641, upon energizing, locks over its right armature and front contact to ground at cam 609 and at its inner left armature and front contact closes a circuit from battery, magnet winding of sequence switch 610, upper left contact of cam 618 (2 to 18), inner left-hand armature of relay 641 to ground at the upper right contact of cam 609 for advancing sequence switch 610 into its normal position 1. With sequence switch 610 in position 1, all operated relays of the test device are released and all lighted lamps are extinguished. The testing circuit is now in normal position.

As soon as sequence switch 610 of the testing device leaves position 18, ground is removed from sleeve conductor 241 at the upper right contact of cam 609 (1½ to 18) and the holding circuit of control relay 200 of the office selector 250 is opened, whereupon relay 200 releases. A circuit is now established for sequence switch 210 extending from battery through the magnet winding of this sequence switch, the lower right contact of cam 207, to ground at the left armature and back contact of relay 200 for advancing the sequence switch out of position 8 into position 18. With sequence switch 210 in position 18 the circuit of the down-drive magnet 212 is established from battery, through the winding of magnet 212 to ground through the lower contacts of cam 209 (18), and through the energization of this magnet, the switch shaft 214 is pressed against the downdrive drum 237 and moved into normal position. Upon reaching its normal position, shaft wiper 219 engages the normal commutator segment 220, whereupon a circuit is established over the upper right contact of cam 207 (3 to 18) and through the magnet winding of sequence switch 210 for advancing the sequence switch into normal position.

As soon as sequence switch 210 leaves position 8½, the holding circuit of control relay 200 of the final selector 250 is opened at the right contact of cam 206 and relay 300 releases, closing a circuit from ground at its right armature and back contact, over the upper left contact of cam 312 to battery through the magnet winding of sequence switch 310 for driving the sequence switch into position 18. With sequence switch 310 in position 18, a circuit is established for the downdrive magnet 335 extending from battery through magnet 335, to ground at the lower contacts of cam 315. The energization of magnet 335 presses the depending

portion of switch shaft 337 against the downdrive drum 363 thereby moving the switch shaft downwardly into its normal position. Upon reaching its normal position shaft wiper 347 engages normal segment 351, whereupon a circuit is established over the lower right contact of cam 312 (18) to battery through the winding of sequence switch magnet 310 for driving the sequence switch 310 into its normal position. The circuits of the office selector 250 and the final selector 350 are now in their normal positions.

15 *Make-busy test of final selector.*

If it is desired to test the final selector switch for accuracy in responding to a busy condition on a final multiple, the test above described is conducted as before but with 20 the make-busy key of the testing device operated. When, therefore, sequence switch 610 of the testing device reaches position 15 and sequence switch 310 of the final selector reaches the testing position 11, the circuit 25 previously traced from battery at the lower left contact of cam 309 and from ground at the upper contacts of cam 317 of the final circuit is established for relays 634 and 663 of the testing device. Relay 634, upon operating, closes a circuit for relay 639 which locks to ground at the lower right contact 30 of cam 616 (15 to 17) as previously described. Relay 639 also closes a circuit for advancing sequence switch 610 from position 35 15 into position 16 as follows: battery, magnet winding of sequence switch 610, lower right contact of cam 653 (15), left armature and front contact of relay 639, conductor 677, outer right spring and alternate contact of the make-busy key to ground at the 40 lower contacts of cam 673 (15). As the sequence switch 610 advances out of position 15 into position 16, relays 634 and 663 release allowing lamp 662 to light.

45 At the final selector when the test brush 340 engages the test terminal 343 of the test line, a reduced potential is encountered since at this time the make-busy key is operated and the test circuit now extends 50 as previously traced through the windings of test relay 302 to test brush 340, test terminal 343, thence over sleeve conductor 346 of the test line, sleeve contact of jack 238, sleeve strand of cord 242, sleeve contact of jack 243, innermost left spring and alternate contact of the make-busy key, outer left spring and alternate contact of said key, 50 ohm resistance 689 to battery and through the inner left spring and alternate 55 contact of the key, resistance 674, resistance 664 to ground at key P. B. X. Test relay 302 does not, therefore, operate and a circuit is closed from battery through the winding of relay 300, lower left contact of cam 316 (1 to 14), lower right contact of

said cam (11 to 13), contact and armature of relay 301, back contact and right armature of relay 302 to ground, advancing sequence switch 310 out of position 11 into position 13. When sequence switch 310 reaches position 12, a circuit is closed from battery through the right winding of relay 301, lower left contact of cam 317 (12 to 13), upper right contact of cam 317 (1 to 15) to ground. With relay 302 deenergized 75 a circuit is now closed from battery at the left armature and back contact of relay 302, left winding of relay 301, upper contact of cam 329 (12 to 13), brush 340 thence as previously traced to ground at the normal contact of key P. B. X. Sufficient current now flows through the left winding of relay 301, aiding the current flowing in its right winding to cause the energization of this relay. Relay 301 now attracts its 80 armature and opens the circuit of relay 300 causing this latter relay to deenergize. The release of relay 300 now completes a circuit from battery, through the winding of sequence switch magnet 310, upper left 85 contact of cam 312 (13), back contact and right armature of relay 300 to ground, moving sequence switch 310 out of position 13 into position 14. In this position relay 300 is energized over a circuit previously traced 90 and causes the advance of sequence switch 310 into position 15, relay 300 locking over conductor 254 to ground at the right contact of cam 206 of the office selector. In 95 position 15 of sequence switch 310 a circuit is established from battery, through the winding of the downdrive magnet 335, upper left and lower right contacts of cam 314 (15), back contact and right armature of relay 302 to ground. Magnet 335, upon 100 energizing, presses the depending portion of the switch shaft 337 against the downdrive drum 363 moving the switch shaft 337 downwardly into its normal position. When the switch shaft reaches normal, the 105 shaft wiper 347 engages the normal position segment 351 closing a circuit over the lower right contact of cam 312 (8 to 16), through the magnet winding of sequence 110 switch 310 for advancing this sequence switch into position 17.

115 Immediately following the movement of sequence switch 310 into position 17 the common circuit including sequence switch 320 is rendered effective to produce successive reversals of current over the talking circuit to produce intermittent operation of the polarized supervisory relay 663 of the testing device. A circuit is first established from battery, right winding of relay 303, lower 120 left contact of cam 328 (17 to 3), assuming that switch 320 is in its normal position, conductor 355, upper right contact of cam 306 (16 to 17), lower left contact of cam 305 (16 to 17), conductor 232, thence as pre- 125 130

viously traced through the windings of relays 634 and 663 of the testing device, returning over conductor 233, lower right contact of cam 307 (16 $\frac{1}{4}$ to 17), conductor 356, 5 right contact of cam 327 (17 to 3), left winding of relay 303, upper contact of cam 322 (17 to 3), winding of coil 323 to ground. It will be noted that the flow of current in this circuit is in such a direction as not to operate 10 polarized relay 663. When the constantly rotating interrupter 325 closes at its metallic segments, a circuit is established from the tone source 326 through the winding of coil 324 to ground. The current flowing in coil 15 324 is induced in the winding 323 and a characteristic tone is transmitted over the circuit through relays 634 and 663 and the left windings of repeating coil 668 which may be heard by the test-man if his head set is at 20 the time connected to the jacks 675 and 690, thus advising him that the final selector has responded properly to the busy test. Relay 303 becomes operated in the circuit above 25 traced and completes a circuit for relay 304, which in turn, closes a circuit from battery through the winding of sequence switch magnet 320, contact of cam 321 (1), contact and armature of relay 304 to ground. The sequence switch 320 leaves position 1 and 30 makes a complete revolution. When sequence switch 320 leaves position 3 it opens the above traced circuit for relay 303 and removes the source of induced tone current. As sequence switch 320 is passing from position 35 3 $\frac{1}{2}$ to position 7 $\frac{1}{2}$, a circuit is closed from battery, through the right winding of relay 303, left contact of cam 327 (3 $\frac{1}{2}$ to 7 $\frac{1}{2}$), conductor 356, lower contact of cam 307 (16 $\frac{1}{4}$ to 17), conductor 233, thence over the 40 circuit traced through the windings of supervisory relays 634 and 663, returning over conductor 232, lower left contact of cam 305 (16 to 17), upper right contact of cam 306 (16 $\frac{1}{4}$ to 17), conductor 355, right contact of cam 328 (3 $\frac{1}{2}$ to 7 $\frac{1}{2}$), left winding of relay 303, lower contact of cam 322 (3 $\frac{1}{2}$ to 7 $\frac{1}{2}$) to ground. The current flowing in this circuit is in the opposite direction and, consequently, polarized supervisory relay 663 is 45 energized to cause the extinguishing of supervisory lamp 662. As sequence switch 320 leaves position 7 $\frac{1}{2}$ the circuit is opened and relay 663 deenergizes to permit the illumination of lamp 662. In positions 8 to 12 of 50 sequence switch 320 the previously traced circuit is closed through the windings of relay 303 and current flows over the talking circuit in the direction opposite to that required for the energization of relay 663. Therefore, this relay remains deenergized and lamp 662 remains lighted. While the 55 sequence switch 320 is moving through positions 12 $\frac{1}{2}$ to 16 $\frac{1}{2}$, the above traced circuit is again completed and current is applied to the talking circuit in the direction necessary 60 to cause the energization of relay 663. The lamp 662 is thus again extinguished. If at the time sequence switch 320 reaches the end of its cycle and passes into position 1, the test-man has not responded to the 65 busy signal indicated by the flashing of lamp 662, relay 303 will be energized and relay 304 will be operated to drive the sequence switch 320 through a second revolution. The flashing of lamp 662 signifies to 70 the test-man that the final selector functions properly on busy tests.

If during the test of the final selector for returning the busy back signal, the cams for connecting battery and ground alternately to 75 the tip and ring conductors 232 and 233 of the final circuit fail to close, thus maintaining supervisory relays 634 and 663 in an open circuit for a period which is longer than should be, relay 634 will establish a circuit 80 for the final open circuit lamp 666 which may be traced from battery, lamp 666, upper right and lower left contacts of cam 667 to ground at the armature and back contact of relay 634. The continued illumination of 85 lamp 666 now apprises the test man of an open circuit condition in the busy back circuit of the final selector. Having completed the make-busy test, the test-man may restore the testing device and the selector switches 90 250 and 350 to normal by operating the disconnect key 672.

P. B. X. test of final selector.

If it is desired to test the final selector 100 for its accuracy in functioning on tests of lines of a P. B. X. group, the P. B. X. key is operated and the test is conducted in the manner previously described up to the point where the sequence switch 310 of the final selector enters its testing position 11 and the sequence switch 610 of the testing device reaches position 15.

In conducting this test the test-man will cause the final selector to select the first 110 set of terminals of the P. B. X. test group, the tip and ring conductors 344 and 345 of the test line being multiplied connected to the tip and ring terminals of each set of the group, and the sleeve conductor 346 of the test line being multiplied to the sleeve terminal of all but the last set of the group. For this purpose it will be assumed that the final selector is driven to terminal 95 through the operation of the 115 No. 9 tens key 407 and of the No. 5 units key 419.

When the test brush 340 engages the test terminal 343 of the first terminal set in the P. B. X. group, it will find this test terminal connected to booster battery since the sleeve conductor 346 of the test line is now connected over the circuit previously traced through the inner left spring and 120 normal contact of the make-busy key, the 125 130

right contacts of cam 615 (2 to 18), winding of relay 601, the right contact of cam 602 (2 to 18), resistance 664 to battery through the alternate contact of the P. B. X. key. The test relay 302 does not, therefore, energize. With relay 302 deenergized and sequence switch 310 in position 11, a circuit is now closed for relay 300 from battery through the winding of relay 300, the lower contacts of cam 316, the armature and back contact of relay 301, the right armature and back contact of test relay 302. Relay 300, upon energizing, establishes a circuit for driving sequence switch 310 out of position 11 into position 13. In passing through position 12 a circuit is established through the right winding of relay 301 to ground, through the lower left and upper right contacts of cam 317, and a circuit is closed from battery at the left armature and back contact of relay 302 left winding of relay 301, upper contact of cam 329 (12 to 13), thence as previously traced to booster battery at the alternate contact of key P. B. X. Current flows in this circuit from the booster battery opposing the current flowing from battery at the contact of relay 302. Relay 301 is therefore energized differentially and does not operate. With sequence switch 310 in position 13 a circuit is now established for the updrive magnet 334 which may be traced from battery, through the winding of magnet 334, the left contact of cam 319 (13), the upper left contact of cam 315 (12 to 13) to ground at the right armature and front contact of relay 300. With magnet 334 energized the switch shaft is driven upwardly in a hunting movement.

When test brush 340 emerges test terminal 364 it again finds this terminal connected to booster battery over sleeve conductor 346 of the test line and the energization of relay 300 is, therefore, maintained for continuing the upward movement of the switch shaft. When test brush 340 engages the test terminal 365, full ground potential is encountered since this test terminal is connected to ground through the low resistance 366 indicating an idle line condition. The current now flowing over the test brush 340 and through the windings of test relay 302 is of sufficient strength to cause the energization of this relay, whereupon the previously traced circuit for relay 300 is opened at the right armature and back contact of relay 302, and relay 300 thereupon releases. Upon the deenergization of relay 300 a circuit is established from the right armature and back contact of relay 300, over the upper left contact of cam 312 (13) for advancing sequence switch 310 out of position 13 into position 14. From this point the circuits of the final selector function as previously described in connection

with the make-busy signal to the testing device. Thus, if the final selector functions correctly in hunting over busy lines of a P. B. X. group and stops when encountering the last line of the group which is idle, the test-man will receive a supervisory signal through the operation of the supervisory lamp 662.

Testing office selectors in conjunction with full mechanical trunks.

Before proceeding with this type of test call, the test man inserts the plugs of cord 248 in the jacks 247 and 249 depresses the "office to full mechanical" key 628, and assuming that the number of the official position in the full mechanical office to which the test call is to be extended is 01-1111, the test-man proceeds to depress the No. 0 office brush key 400, the No. 1 office group key 401, the No. 1 thousands key 415, the No. 1 hundreds key 416, the No. 1 tens key 417 and the No. 1 units key 418. The test-man then depresses the start key 607. If the office selector to be tested is not busy the testing device functions as described for the preceding test and office brush and group selections are accomplished exactly as hereinbefore described, the sequence switch 210 of the office selector advancing to position 5 and sequence switch 610 of the testing device advancing to position 5 upon the completion of office group selection. With sequence switch 210 in position 5 the office selector control relay 200 becomes energized over the left contacts of cam 209 (5) and advances sequence switch 210 into the trunk hunting position 6. Trunk hunting now proceeds until the selected set of brushes encounters the terminals of an idle trunk extending to the desired full mechanical office, when relay 200 becomes deenergized advancing sequence switch 210 into position 7. With sequence switch 210 in position 7, relay 200 again energizes and locks over its right armature and front contacts the left contacts of cam 205, over conductor 241 to ground at cam 609 of the testing device and, upon energizing, drives sequence switch 210 into the trunk closing position 8.

With sequence switch 210 in position 8 and sequence switch 610 in position 5 the circuit hereinbefore traced extending to the brushes 215 and 216 of the office selector 250 and through the windings of trunk testing relay 652 and the winding of the control relay (not shown) of the selected incoming selector, is closed with the 1500 ohm resistance 676 omitted, since at this time resistance 676 is shunted at the outer right spring and alternate contact of key 628. Relay 652 operates in this circuit closing an obvious circuit for relay 637, which in turn, closes a circuit from ground at its right armature and front contact over the upper

right contact of cam 653 (5), for driving sequence switch 610 out of position 5 and into position 6. As sequence switch 610 leaves position 5 the circuit of relay 652 is opened 5 at the left contact of cam 624 and this relay releases, releasing relay 637. The office group lamp 651 is now extinguished since its circuit is opened at the lower right contact of cam 609 (4 to 5) upon the movement of sequence switch 610 out of position 5.

With sequence switch 610 in position 6 a fundamental circuit is established as hereinbefore traced through the windings of 15 stepping relay 500 and the right winding of overflow relay 501 to the brushes 215 and 216 of the office selector and from thence to battery and ground at the selected incoming selector through the winding of the 20 control relay thereof. The incoming and final selector through which the test call is established may be of the type disclosed in the patent to F. A. Stearn and F. J. Scudder No. 1,395,977, issued November 1, 1921. 25 Relay 500 and the control relay of the incoming selector now operate, relay 500 closing a circuit for the No. 0 counting relay 502 from battery, lower contact of cam 511, winding of relay 502, No. 0 lead 513, No. 0 30 lead 420 Fig. 4, key 415, conductor 421, inner left spring and alternate contact of key 628, conductor 520, lower left contact of cam 514 (6), conductor 516 to ground at the armature and contact of relay 500. The incoming 35 selector functions upon the operation of its control relay in the well known manner to revert impulses during its brush selection movement for repeatedly deenergizing and energizing stepping relay 500. 40 Upon the first deenergization of relay 500, relay 503 energizes in parallel with relay 504 driving sequence switch 610 into position 7 and opening the fundamental circuit to arrest the movement of the switch shaft 45 of the incoming selector. As sequence switch 610 advances out of position 6 the operated counting relays release. At the incoming selector the first set of brushes has now been selected.

50 Sequence switch 610 is now advanced out of position 7 into position 8 over a circuit from battery through the magnet winding of switch 610, lower left contact of cam 649 (7) to ground at the outer left spring and alternate contact of key 628. As sequence switch 610 leaves position 7 the circuit of incoming brush progress lamp 654 is opened indicating that no fault has occurred in incoming brush selection. As soon as sequence switch 610 reaches position 8 the circuit of incoming group progress lamp 655 is closed as before described. With sequence switch 610 in position 8 the fundamental circuit is again established for controlling the incoming selector in its group selection movement,

the particular group selected being dependent upon the particular thousands and hundreds keys depressed. Relay 500 now energizes over the fundamental circuit and closes a circuit for the No. 2 counting relay 529 from battery, upper left contact of cam 512 (8), winding of relay 529, armature and back contact of relay 530, lead 531, lead 422 (Fig. 4) inner right spring and alternate contact of hundreds key 416, conductor 423, 75 inner left contact of thousands key 415, conductor 424, inner right spring and alternate contact of key 628, conductor 521, lower right contact of cam 514 (8), conductor 516 to ground at the armature and contact of relay 500. Impulses from the group selection commutator of the incoming selector, during the incoming group selection movement, now repeatedly energize and deenergize relay 500 until the No. 0' counting relay 503 80 operates in parallel with relay 504, when sequence switch 610 is advanced out of position 8 into position 9, and the fundamental circuit is opened to arrest the movement of the switch shaft of the incoming selector. 85 As the sequence switch 610 advances out of position 8, the operated counting relays release. At the incoming selector during the group selection movement the first set of brushes has been tripped and moved to the 90 bottom of the third group of contacts in the portion of the bank to which they have access.

The sequence switch 610 is now advanced out of position 9 into position 10 over the 100 circuit traced to ground at key 628, and in moving out of position 9 opens the circuit of incoming group progress lamp 655 at the upper left contact of cam 659 (8 to 9). Upon reaching position 10 sequence switch 610 closes a circuit for final brush progress lamp 656 at the upper right contact of cam 659 (10 to 11). The extinguishing of lamp 655 indicates that no fault has occurred in 105 making incoming group selection. The incoming selector now functions in the well-known manner to hunt for an idle trunk circuit extending to a final selector having access to the line 1111. As soon as such idle 110 trunk is found the fundamental circuit is established through the control relay of the selected final selector and the windings of stepping relay 500 at the testing device. Relay 500 now energizes and as the hundreds key 416 has been operated the No. 1 115 counting relay 517 is operated over a circuit from battery, upper right contact of cam 512 (10), winding of relay 517, armature and back contact of relay 518, lead 519, lead 425 Fig. 4, outer right contact of hundreds key 416, conductor 410, lower left contact of cam 515 (10), conductor 516 to ground at the armature and contact of stepping relay 500.

120 At the final selector the closure of the 130

fundamental circuit causes the movement of the switch shaft upwardly in a brush selection movement. During this movement impulses are reverted to repeatedly deenergize and energize relay 500 until the No. 0' counting relay 503 energizes in parallel with relay 504, when the fundamental circuit is opened to arrest the switch shaft of the final selector, and the previously traced circuit is closed for advancing sequence switch 610 out of position 10 into position 11. As the sequence switch 610 leaves position 10 the locking circuits of all operated counting relays are opened and such relays release. At the final selector the second set of brushes has been selected to be tripped upon a subsequent movement of the switch shaft during the group selection movement thereof.

Sequence switch 610 is now advanced out of position 11 into position 12 over the circuit previously traced to ground at key 628 and, in moving out of position 11, opens the circuit of the final brush progress lamp 656 at the upper right contact of cam 659 (10 to 11). Upon reaching position 12 sequence switch 610 closes the circuit of the final tens progress lamp 657 over the lower right contact of cam 659 (12 to 13). The extinguishing of lamp 656 indicates that no fault has occurred in making the final brush selection. With sequence switch 610 in position 12 the fundamental circuit is again established and at the final selector the switch shaft is again driven upwardly in its group selection movement, the selected brushes being tripped at the beginning of such movement. Relay 500 also operates over the fundamental circuit and at its armature and contact closes a circuit for the No. 1 counting relay 517 as follows: battery, upper right contact of cam 512 (12), winding of relay 517, armature and back contact of relay 518, lead 519, lead 426 Fig. 4, left contact of key 418, conductor 414, upper left contact of cam 515 (14), conductor 516 to ground at the armature and contact of relay 500. Upon successive deenergizations of relay 500 the counting relays operate in succession until the No. 0' relay 503 energizes in parallel with relay 504, when the fundamental circuit is opened to arrest the movement of the switch shaft of the final selector, and the previously traced circuit is established for advancing sequence switch 610 out of position 14 into position 15. When sequence switch 610 leaves position 14 all operated counting relays are released.

At the final selector the brush shaft moves in its group selection movement reverting impulses back for shunting relay 500 until the No. 0' counting relay 503 energizes in parallel with relay 504, when sequence switch 610 is advanced into position 13 and the fundamental circuit is opened to arrest the movement of the switch shaft of the final selector. The selected brush sets of the final selector have now been positioned beneath the second group in the bank to which they have access. As sequence switch 610 leaves position 12 the locking circuits of all operated counting relays are opened and these relays release. The sequence switch 610 is now advanced out of position 13 into position 14 over the circuit previously traced to ground at key 628 and in

moving out of position 13 opens the circuit of the final tens progress lamp 657, indicating that no fault has occurred in making final tens selections. Upon reaching position 14 sequence switch 610 closes the circuit of the final units progress lamp 658 as previously traced.

With sequence switch 610 in position 14 the fundamental circuit is again established, and at the final selector the switch shaft is again driven upwardly in its units selection movement. As the switch shaft moves upwardly, impulses are reverted over the fundamental circuit for causing the repeated deenergization of stepping relay 500. Upon the first energization of relay 500 with No. 1 units key 418 depressed a circuit is established for the No. 1 counting relay 517 from battery, upper right contact of cam 512 (14), winding of relay 517, armature and back contact of relay 518, lead 519, lead 426 Fig. 4, left contact of key 418, conductor 414, upper left contact of cam 515 (14), conductor 516 to ground at the armature and contact of relay 500. Upon successive deenergizations of relay 500 the counting relays operate in succession until the No. 0' relay 503 energizes in parallel with relay 504, when the fundamental circuit is opened to arrest the movement of the switch shaft of the final selector, and the previously traced circuit is established for advancing sequence switch 610 out of position 14 into position 15. When sequence switch 610 leaves position 14 all operated counting relays are released.

At the final selector the selected line is tested and if found to be idle, as will be assumed, the sequence switch of the final selector advances to the talking position 15 and in so doing advances the sequence switch of the incoming selector to position 9 for reversing battery and ground connections to the tip and ring conductors of the incoming circuit as is fully shown and described in the Patent No. 1,395,977 above referred to. With sequence switch 610 in position 15 the supervisory lamp 662 lights over a circuit from battery, lamp 662, back contact and armature of polarized relay 663, armature and back contact of relay 635 to ground at the lower right contact of cam 616 (15 to 17), and sleeve lamp 661 lights over a circuit from battery, lamp 661, inner right spring and normal contact of the make-busy key, outer right armature and back contact of relay 640, to ground at the upper left contact of cam 650 (15). Lamp 665 also lights in a circuit from battery, lamp 665, left contacts of cam 667, left armature and back contact of relay 639, conductors 677, 678 and 679, normal contacts of keys 630 and 623 to ground at the lower contacts of cam 673 (15). As soon as current is reversely connected at the incoming

selector the previously traced circuit from the brushes 215 and 216 of the office selector, through the windings of supervisory relays 634 and 663 is established with current flowing in the proper direction to operate both of these relays. Relay 663, upon operating, momentarily opens the circuit of supervisory lamp 662 but the extinguishing of this lamp at this time is disregarded. Upon the energization of relay 634 the previously traced circuit of relay 639 is closed and relay 639 locks over its right armature and contact to ground at the lower right contact of cam 616, and at its left armature and back contact opens the circuit of lamp 665. The circuit is now established by relay 639 at its left armature and front contact for advancing sequence switch 610 into position 16. 10

As sequence switch 610 leaves position 15 the circuit of the final units progress lamp 658 is opened and this lamp is extinguished to indicate that final units selection has been completed without fault. The circuit for supervisory relays 634 and 663 is also opened 15 as sequence switch leaves position 15 and supervisory lamp 662 again lights. As sequence switch 610 enters position 16 relay 640 operates over a circuit from battery, winding of relay 640, lower contacts of cam 20 622 (16 to 17), conductor 677 to ground at the upper right contact of cam 669 (16), and locks to ground over its inner right armature and front contact, and at its outer right armature and back contact opens the 25 circuit of sleeve lamp 661. The extinguishing of sleeve lamp 661 indicates to the test-man that the incoming selector has advanced and that ringing current has been connected to the called line at the incoming selector. 30 The switch 610 is now advanced to position 17 by a circuit from battery through its magnet winding, lower left contact of cam 649 (16) to ground at the outer left spring and alternate contact of key 628. 35 At the incoming selector the sequence switch advances immediately out of position 9 and into the ringing position 11, since its control relay finds a circuit through the windings of supervisory relays 663 and 634 40 of the testing device. Current now flowing through the windings of these relays during the ringing period is in a direction opposite to that required for operating polarized relay 663 and, therefore, only relay 634 remains operated and supervisory lamp 662 remains lighted. When the called party which 45 may be a test-man at the test or wire chief's position in the machine switching office to which the connection has been extended, responds to the application of ringing current the ringing current at the incoming selector is tripped in the well known manner and the supervisory relay of the incoming circuit energizes over the called line loop, reversing 50 the battery and ground connections to the tip and ring sides of the incoming circuit. The current now flowing through the winding of polarized relay 663 of the testing device is in such a direction as to cause its energization and the consequent extinguishing of the supervisory lamp 662. The test-man noting the extinguishing of lamp 662 knows that the connection has been successfully established through the office selector under test. The test-man may now 55 talk over the established connection, if he so desires by plugging his head-set (not shown) into the jacks 673 and 690. 70

When the receiver at the called line is replaced on the switchhook, battery and ground connections are again reversed at the incoming selector and polarized relay 663 again deenergizes lighting supervisory lamp 662 as a disconnect signal. The test-man now operates the disconnect key 672 80 causing the release of the operated apparatus of the testing device and the release of the operated selector switches in the manner 85 previously set forth. 90

This same test may now be repeated if desired with the same number set up on the keyboard for again testing the office selector for selecting another idle trunk extending to the same machine switching office. The test-man may set up successively other designations upon the keyboard for operating the office selector under test to select other trunk groups extending to other machine switching offices to which it has access, each 95 of the tests being conducted in the manner 100 just described. It is to be noted that the keys of the keyboard are not automatically released at the end of each of the foregoing tests, but remain in their set positions unless released through the depression of other 105 keys in the several rows in setting up the different designations. 110

Should the office selector under test go to the overflow position while trunk hunting with sequence switch 610 of the testing device in position 4 reversed current is sent back over the fundamental circuit from the office selector as follows: When the switch shaft 214 of the office selector reaches the upper limit of its movement, the sequence 115 switch 210 is advanced immediately out of the trunk hunting position 6 into position 8 over a circuit from battery, magnet winding of switch 210, upper left contact of cam 207 (1 to 7), overflow segment 256 to ground on wiper 218. In leaving position 6 the circuit of updrive magnet 211 is opened to arrest the upward movement of the switch shaft. The brushes 215 and 216 now rest on overflow terminals of the switch bank, battery being connected to the ring terminal and thus over the upper contacts of cam 204 (8) to conductor 240, and ground being connected to the tip terminal and thus over the upper contacts of cam 201 (8) to conductor 125 130

239. The current now flowing over the fundamental circuit through the right winding of overflow relay 501 is in such a direction as to supplement the current flowing through the left winding of this relay and relay 501 thus becomes energized. Relay 501 at its armature and contact closes a circuit for relay 509 from battery, winding of relay 509, armature and contact of relay 501 to ground at the lower left contact of cam 616 (4 to 14), relay 509, upon energizing, locking to ground at cam 616 through its inner right armature and front contact. A circuit is now closed for advancing the sequence switch 610 out of position 4 into position 14 as follows: battery, magnet winding of switch 610, conductor 533, the outer right armature and front contact of relay 509, conductor 534 to ground at the lower right contact of cam 669 (4 to 13). With sequence switch 610 in position 14 a circuit is established through the overflow lamp 535 to ground at the lower left contact of cam 659 (14 to 15). The test-man now restores the circuit by operating the disconnect key 672 in the manner previously described.

Should the incoming selector go to its overflow position, current is reversely connected to the fundamental circuit at the brushes of the incoming selector, and the testing device functions in the same manner as described in connection with the office selector overflow except that the overflow relay 501 operates when sequence switch 610 is in position 8.

Testing office selector in conjunction with trunks to manual office equipped with relay call indicator-step-by-step method.

40 To test an office selector in conjunction with a group of trunks outgoing therefrom to a manual office operating on a relay call indicator basis, the test man operates the "office to RCI" key 621 and records on the 45 keyboard of the testing device the office brush and office group designations necessary to route the test call to the particular manual office desired, and the numerical designation of a line in such manual office, 50 which may for convenience in making such tests terminate on a test or wire chief's position of such office. He also depresses the "step-by-step" and starting keys 611 and 607. The office selector functions in the 55 manner previously described in its brush and group selections in accordance with office brush and office group designations recorded on the keyboard, and proceeds to hunt for an idle trunk extending to the 60 manual office.

Following the office group selection, the sequence switch 610 advances into position 5 and the fundamental circuit is established as previously described, but in this instance 65 through the windings of the control relays

of the manual trunk circuit, the winding of the trunk test relay 652 of the testing device and through resistances 676 and 680 having a total resistance of 16,000 ohms. The trunk circuit to which the connection is extended by the office selector 250 and the call indicator circuits associated therewith may be of the type disclosed in the application of A. E. Lundell and E. H. Clark Serial No. 387,531, filed June 9, 1920. The sensitive control relay of the trunk circuit and relay 652 energize over the fundamental circuit if the trunk is in standard condition, but due to the high resistance at the testing device the marginal control relay of the trunk circuit does not operate. Relay 652, upon operating, closes an obvious circuit for relay 637 which advances sequence switch 610 out of position 5 into position 6, and at its left armature and front contact closes a circuit for maintaining the fundamental circuit through relay 652 with the resistances 676 and 680 excluded. The circuit for relay 652 may now be traced in part from conductor 252, lower armature and back contact of relay 619, the left contact of cam 620 (5 to 6), winding of relay 652, the left armature and front contact of relay 637, the intermediate right spring and alternate contact of key 621, the intermediate armature and back contact of relay 619, conductor 625, normal contact of key ADJ to conductor 253. With sequence switch 610 in position 6 a shunt is also connected around the winding of relay 652 which may be traced from the upper contacts of cam 620, the innermost left spring and alternate contact of key 621, the right contact of cam 681 (6), resistance 682, conductor 505, resistance 506, and the right winding of relay 501 in parallel, winding of stepping relay 500, armature and back contact of relay 503, conductor 507, the right contact of cam 683 (2 to 6), the innermost right spring and front contact of key 621, the lower right contact of cam 624 (6 to 14), the intermediate right spring and alternate contact of key 621, the left armature and front contact of relay 637 to the other terminal of relay 652. The current now flowing over the fundamental circuit is sufficient to operate the marginal control relay of the trunk circuit, causing the lighting of the assignment lamp in the well known manner. Sequence switch 610, upon leaving position 5, opens the circuit of the office group progress lamp 651 and upon entering position 6 closes the circuit of the incoming brush progress lamp 654. Both the office brush and office group progress lamps will have lighted and become extinguished if no fault has occurred in the setting of the office selector under test.

When the operator at the manual position operates the assignment key of the trunk circuit to associate the trunk circuit with the

- indicator of her position, the trunk circuit will be momentarily opened and relays 652 and 637 will, consequently, release. Relay 637, upon releasing, closes a circuit from 5 ground at its right armature and back contact over the intermediate left spring and alternate contact of key 621, the upper left contact of cam 653 (6) to battery through the magnet winding of sequence switch 610
- 10 for advancing the sequence switch out of position 6 into position 7. With sequence switch 610 in position 7 a circuit is established for advancing the impulser sequence switch 510 out of position 1 through 15 intermediate positions into position 17 for transmitting code impulses over the fundamental circuit through the control relays of the operator's call indicator. The circuit for advancing switch 510 may be traced 20 from battery, magnet winding of switch 510, the upper left contact of cam 536 (1), conductor 537, the outer left spring and contact of key 621 to ground at the upper left contact of cam 684 (7). Code impulses are 25 now transmitted in the following order, ten thousands, thousands, hundreds, tens and units. Four circuit conditions are established by switch 510 for each digit of the line designation, the first and third conditions being either an open circuit condition 30 or the transmission of a light positive impulse current, and the second and fourth conditions being the transmission of either light or heavy negative impulses of current.
- 35 For example, if the ten thousand's designation is 1 the following circuit conditions will be established during the rotation of switch 510 from position 1 through position 3 $\frac{1}{2}$: As switch 510 passes through positions 40 1 to 1 $\frac{1}{2}$, a light positive impulse is transmitted from battery, lower left contact of cam 512 (7), resistances 538 and 539, upper left contact of cam 540 (1 to 2 $\frac{1}{2}$), contact of cam 541 (18 $\frac{1}{2}$ to 3), contact of ten thousand's key 427, lead 428, lead 542, contacts of cam 543, conductor 544, upper left contact of cam 683 (7), innermost right spring and alternate contact of key 621, lower right contact of cam 624 (6 to 14), thence over the fundamental circuit and returning through the upper right contact of cam 620 (6 to 14), innermost left spring and alternate contact of key 621, lower contact of cam 681 (7), conductor 546, the lower contact of cam 547 (1 to 1 $\frac{1}{2}$), conductor 548 to ground at the lower right contact of cam 650 (7). As the impulser passes through positions 1 $\frac{1}{2}$ to 2, the next impulse of light negative current is transmitted from battery at the lower left contact of cam 512 (7), resistance 549, upper contact of cam 550, conductor 546, thence as traced over the fundamental circuit and returning over conductor 544, the upper contact of cam 547, conductor 548 to ground at 60 the lower right contact of cam 650 (7). As the impulser passes through positions 2 $\frac{1}{2}$ to 2 $\frac{3}{4}$, the fundamental circuit is not closed being open at the upper contact of cam 543. As the impulser passes through positions 3 $\frac{1}{4}$ to 3 $\frac{1}{2}$ the next light negative impulse is sent 70 over the same path as described for the transmission of the second impulse of light negative current.
- In the same manner impulses are transmitted in accordance with the thousands, 75 hundreds, tens and units digits recorded by depressed keys of the keyboard, the impulser moving into position 17 upon the transmission of the last impulse of the units digit. A circuit is now closed for advancing sequence switch 610 into position 17 which 80 may be traced from battery, magnet winding of switch 610, upper right contact of cam 649 (7 to 16) to ground at the contact of cam 545 (17). With sequence switch 610 in position 17 the impulser 510 is advanced 85 to its normal position over a circuit from battery, magnet winding of impulser 510, right contact of cam 536 (17), conductor 551 to ground at the lower contact of cam 684 (17). With sequence switch 610 in position 17 the previously traced circuit is established 90 for the supervisory lamp 662.
- With sequence switch 610 in position 17 the supervisory relays 634 and 663 are connected over the brushes of the office selector 250 to the selected trunk circuit and, as soon as the operator noting the line designation displayed upon her indicator, completes the connection to the designated call line, these 100 relays become connected in series with the control relays of the trunk circuit. Ringing current is then applied to the called line in the usual manner. When the called party answers, battery and ground connections are 105 reversed at the trunk circuit through the operation of the calling supervisory relay and the current flowing over the circuit through the supervisory relays of the testing device is now in such a direction as to cause the 110 operation of the polarized relay 663. Relay 663 thereupon extinguishes the supervisory lamp 662. When the receiver of the station of the called line is restored, current is again reversed at the trunk circuit and polarized 115 relay 663 releases, closing the circuit of lamp 662 which now lights as a disconnect signal.
- The test-man now proceeds to restore the circuits through the operation of the disconnect key 672 in the manner hereinbefore described. The same call may be repeated if desired to test the office selector for its ability to hunt for and seize other trunks in the same trunk group. Ability 120 of the office selector to select idle trunks in other trunk groups extending to the other manual offices of the exchange to which it has access may be tested in a similar manner by employing other office and line designations.
- 125 130

Testing final selector only-step-by-step method.

To test a final selector only, the test-man inserts the calling plug of cord circuit 248 in the make-busy jack 244 of the final selector to be tested and depresses the "final only" key 623. The insertion of the plug of cord circuit 248 in jack 244 connects ground through jack contacts 246, over conductor 234, to the multiples of test terminal 229, to mark the selected final selector as busy to all office selectors having access thereto, and disconnects sleeve conductor 234 from the sleeve conductor 254. If the final selector is busy ground potential will be encountered on conductor 254 from ground at the upper left and lower right contacts of cam 311 and in the manner previously described, the sleeve relay 601 of the testing device will operate to close a circuit for the busy lamp 603. If the final selector is idle, as will be assumed, no ground potential is encountered and relay 601 does not operate. Ground potential is now applied to the sleeve conductor 254 to hold the selected final busy over the sleeve of jack 244 and to ground at the lower contacts of cam 602 (1) and later to ground at the upper right contact of cam 609 (13 to 18) as previously described.

The test-man now sets up a designation, for example, 97 upon the tens and units keys of the keyboard for directing the test call through the final selector to the terminals of the test line and depresses the "step-by-step" key 611 and the start key 607. The operation of the start key 607 causes the advance of the sequence switch 610 into position 2 as previously described, from which position, it immediately advances into position 6 over a circuit from battery, magnet winding of switch 610, lower left contact of cam 653 (2 to 5) to ground at the inner right spring of key 623. The circuits function from this point in exactly the same manner as previously described in connection with the combined office and final selector test except that with the "final only" key 623 depressed, the fundamental circuit, extends over the upper contacts of cam 673 and the left alternate contact of key 623 rather than over the upper contacts of cam 622 and the left normal contact of key 623.

Testing distant-district selector-step-by-step method.

To test a distant-district selector, the patching cord 248 is plugged into jack 247 of the testing device and into the make-busy jack 251 of the district 150 to be tested, and the cord circuit 242 is plugged into jack 243 of the testing device and into jack 238 of the test line, the test line being selected

for this test through the operation of the distant-district under test, an office selector and a final selector. The test-man thereupon depresses the "distant-district" key 612 which establishes an operating circuit 70 for relays 428 and 429 from battery, through the windings of these relays, conductor 430 to ground at the intermediate left spring and contact of key 612. A circuit is also established for relays 631 and 619 from 75 battery, through the windings of these relays to ground at the outer left spring and contact of key 612. Relay 631, upon energizing, disconnects the polarized supervisory relay 663 from series connection with the windings of supervisory relay 634, and connects relays 635 and 636 in series with the lower winding of relay 634 for a purpose to be later described. Relay 619, upon energizing, removes the shunt from around resistances 632 and 633 to compensate the resistance in the fundamental circuit extending to the district selector under test. The operation of relay 631 also closes a circuit for the key release magnets 431 to 436, inclusive, which may be traced from ground through these magnets in parallel, conductor 437, the upper armature and front contact of relay 631 to battery at the lower right contact of cam 512 (1), causing the release 95 of any keys which are at the time depressed. The operation of relays 428 and 429 connects the leads represented by the circles connected to the armature contacts thereof, which are cross connected to the counting 100 relay leads of Fig. 5, to the contacts of cams 514 and 515.

The test-man now operates the start key 607 which closes a circuit for relay 648 from battery, winding of relay 648, innermost 105 right spring and alternate contact of key 612, inner right armature and back contact of relay 613, conductor 614, contact of key 607, left contacts of cam 615 (1), armature and back contact of relay 601, conductor 605 110 to ground at the outer right armature and back contact of relay 606. Relay 648 closes a circuit for relay 606 from battery through the winding of relay 648, the outer right armature and back contact of relay 613, winding of relay 606 to ground at the armature and front contact of relay 648, but relay 606 being shunted does not energize until key 607 is released. When key 607 is released, relay 606 energizes and closes a circuit for the lamp 685 to indicate that tandem hundreds impulses are being transmitted to the distant-district selector. Relay 606 also closes an obvious circuit for relay 647 which locks through its right armature and contact, the armature and back contact of relay 608, to ground at the upper right contact of cam 616 (17 to 1).

A fundamental circuit is now established including the windings of the stepping re- 130

lay 500 of the testing device and the winding of the control relay 102 of the district selector under test, which may be traced from battery, winding of relay 102, left contact of cam 128 (1 to 3), conductor 155, tip of jack 251, tip strand of cord circuit 248, tip of jack 247, conductor 253, normal contact of key ADJ, conductor 625, resistance 633, outer left armature and contact of relay 606, conductor 507, armature and back contact of relay 503, windings of relay 500, resistance 506 and right winding of relay 501 in parallel, inner left armature and contact of relay 606, resistance 632, conductor 252, ring of jack 247, ring strand of cord circuit 248, ring of jack 251, conductor 156, upper contact of cam 137 (1 to 3), to ground at the upper left contact of cam 139 (1 to 16). Relay 102 becomes energized and closes a circuit from ground through its right armature and front contact, upper contacts of cam 134, right winding of relay 101 to battery. Relay 101 attracts its armatures and closes a circuit from battery, through the winding of sequence switch magnet 100, lower left contact of cam 143 (1), front contact and left armature of relay 101, left contacts of cam 139 to ground, driving sequence switch 100 out of position 1 into position 2.

Provided the sender selector sequence switch 110 is standing in a position corresponding to a busy register sender, relay 101 is maintained energized in position 2 of sequence switch 100 by means of a circuit from battery through the left winding of said relay, upper right contact of cam 135 (1 to 2), front contact and outer right armature of relay 101, upper contact of cam 141 (1 to 3), thence over one or another of the multiple contacts of cams 153, 158, 159 or 160 depending upon the position in which the sender selector switch 110 is standing, to the lower right contact of cam 138 (3 to 15) of the district switch that is maintaining the sender busy, upper left contact of cam 139 (1 to 16) at such switch to ground. Relay 101 by remaining energized provides a circuit from battery, through the winding of sequence switch magnet 110, upper contact of cam 142 (2), front contact and left armature of relay 101, left contacts of cam 139 to ground. Sequence switch 110 commences to rotate in search of an idle register sender. As the sender sequence switch 110 passes through its quarter positions, a momentary circuit is established from ground through the contact of cam 161, upper right contact of cam 146 (2), lower contact of cam 144 (2 to 13), inner right armature and contact and right winding of relay 101 to battery. This maintaining circuit is provided to prevent relay 101 from releasing, arresting the movement of switch 110 provided a register sender becomes idle at the instant

when said sequence switch has just passed the position corresponding to such sender. In other words, the maintaining circuit provided by cam 161 insures that the sequence switch 110 will continue to rotate until it reaches a position corresponding to a register sender which is at the time idle, thus preventing an incorrect positioning of the sender sequence switch.

It will be assumed that the sender indicated in the dotted rectangle, is the first idle one to be encountered, and that this sender is represented by position 1 of the sender selector 110. When, therefore, the sender selector reaches position 1, the circuit of relay 101 is opened and the relay releases its armatures to open the driving circuit of said sender selector. Relay 101, moreover, completes a circuit from battery through the winding of sequence switch magnet 100, lower right contact of cam 143 (2), back contact and left armature of relay 101 to ground through the left contacts of cam 139. Sequence switch 100 moves to position 3 and from positions 3 to 15 renders the selected sender busy by means of a circuit from ground, through the upper left contact of cam 139 (1 to 16), lower right contact of cam 138 (3 to 15), thence in multiple through the lower right contact of cam 153 (14 to 15) of all other sender selectors similar to 110.

A circuit is now established from ground at the upper left contact of cam 139, lower right contact of cam 138 (3 to 15), lower contacts of cam 153, and a second circuit from ground at the right armature and front contact of relay 102, upper left and lower right contacts of cam 134, lower right contact of cam 148, to the selected register sender in the manner disclosed in the patent to E. W. Hancock, No. 1,439,735, above referred to, causing the selected sender circuits to function to prepare the sender for operation. A circuit is thereupon established from the sender over the lower right contact of cam 147 (1), conductor 164, the upper left contact of cam 132 (3), through the magnet winding of sequence switch 100 for advancing it to position 4. With sequence switch 100 in position 4, a circuit is closed from battery through the right winding of relay 101, lower left contact of cam 145 (4), upper right contact of cam 144 (4) to ground. Relay 101 attracts its armatures and completes a circuit from battery through the winding of sequence switch magnet 100, lower left contact of cam 143 (4), front contact and left armature of relay 101 to ground at the left contacts of cam 139. Sequence switch 100 moves into position 5 from whence it is driven into position 6 by means of a circuit including the lower right contact of cam 132, and from position 6 into position 7 over a circuit closed at the con-

tact of cam 133. As soon as sequence switch 100 leaves position 3 the original circuit of relay 102 is opened at the left contact of cam 128, but this relay remains energized in the fundamental circuit, from battery through the winding thereof, contact of cam 129 (3 to 7), outer left armature and contact of relay 102, lower contact of cam 131 (3 to 7), upper contact of cam 130 (3 to 13), thence over conductor 155 as previously traced, returning by way of conductor 156, upper contacts of cam 136, lower contact of cam 149 (1) to ground at the selected sender in the manner fully described in the aforesaid patent. The tandem hundreds register of the selected sender now commences to rotate and in rotating intermittently shunts down the stepping relay 500 of the testing device, holding relay 102 of the district selector energized.

Upon the first energization of stepping relay 500 in the fundamental circuit above traced, a circuit is established for the No. 0 counting relay 502, it being assumed that the tandem hundreds digit 0 is to be selected. The circuit for relay 502 may be traced from battery, lower contact of cam 511 (1), winding of relay 502, lead 513, lead 438 Fig. 4, outer right armature and contact of relay 429, conductor 439, outer left armature and contact of relay 647, outer right spring and contact of key 612 to ground at the armature and contact of stepping relay 500. Relay 502 locks in series with relay 503. Upon the first deenergization of relay 500 when the tandem hundreds register of the sender has advanced one step, relays 503 and 504 energize in series with relay 502, relay 503 opening the fundamental circuit and relay 504 closing a circuit from ground at its armature contact, the innermost left spring and contact of key 612, to battery through the winding of relay 613. Relay 613 energizes and locks through its inner left armature and contact to ground at the upper left contact of cam 669 (1 to 16). Relay 613 also opens the holding circuit of relays 606 and 648 causing their release, and closes a circuit for relay 642. The circuit of relay 642 extends from battery, through the winding of relay 642, intermediate right spring and contact of key 612, outer left armature and contact of relay 613 to ground at the back contact and armature of relay 648. Relay 606, upon releasing, now opens the previously traced fundamental circuit and extinguishes lamp 685 indicating that no fault has occurred in making tandem hundreds selection. The office brush progress lamp 626 now lights in a circuit from battery through this lamp, inner left armature and contact of relay 647 to ground at the inner right armature and back contact of relay 606. Relay 642, upon operating, locks through its inner right armature and front contact to

ground at the outer left armature and back contact of relay 641, but performs no useful function.

At the district selector under test the opening of the fundamental circuit at the contacts of relay 606 and contacts of relay 503, permits the release of relay 102, which upon deenergizing, opens at its right armature and front contact the circuit extending to the sender for controlling the advance of the tandem hundreds register, whereupon the register is arrested. The circuits of the sender are now prepared for the reception of the tandem tens registration, awaiting the closure of the fundamental circuit at the testing device. The test-man now operates start key 607 closing a circuit for relay 608 from battery through the winding of relay 608, the inner right armature and front contact of relay 613, conductor 614, contact of key 607, left contacts of cam 615 (1), armature and back contact of relay 601, conductor 605 to ground at the outer right armature and back contact of relay 606. Relay 608 opens the circuit of relay 647, which releases, and opens the circuit of lamp 626. The lighting and extinguishing of lamp 626 is to be disregarded at this time. Upon the release of key 607, relay 617 energizes in the locking circuit of relay 608 and advances sequence switch 610 into position 2. Relays 608 and 617 now release. With sequence switch 610 in position 2 the operated counting relays release and a circuit is established for the office brush or tandem tens progress lamp 626 extending from battery through the lamp 626 to ground at the upper left contact of cam 669 (2 to 3). The fundamental circuit is again established from battery through the winding of the control relay of the sender, lower right contact of cam 154 (1), contacts of cam 130, conductor 155, thence as previously traced through the windings of stepping relay 500 of the testing device, returning over conductor 156, upper contacts of cam 136, lower contact of cam 149 (1) to ground at the sender. The control relay of the sender now establishes an operating circuit for advancing the tandem tens register, which during its operation, functions to momentarily shunt the stepping relay 500 of the testing device.

Upon the closure of the fundamental circuit, relay 500 energizes and closes a circuit for the No. 0 counting relay 502, it being assumed that the tandem tens digit 0 has been selected. The circuit for relay 502 may be traced from battery, lower contact of cam 511 (2), winding of relay 502, lead 513, lead 440 Fig. 4, outer left armature and contact of relay 428, conductor 404, upper left contact of cam 514 (2), conductor 516 to ground at the armature and contact of relay 500. Relay 502 locks in series with relay 503. Upon the first deenergization of re-

lay 500 when the tandem tens register advances one step, relay 503 energizes in parallel with relay 504 in the locking circuit of relay 502, relay 503 opening the fundamental circuit and relay 504 advancing the sequence switch 610 out of position 2 into position 3. As sequence switch 610 leaves position 2 the operated counting relays are released. With sequence switch 610 in position 3 the test-man again operates the start key 607, operating relays 608 and 617 to advance the sequence switch 610 into position 4. Sequence switch 610, upon leaving position 3, extinguishes lamp 626 indicating that no fault has occurred in tandem tens selection and upon reaching position 4 lights office group or tandem units lamp 651. At the sender the tandem tens register is arrested upon the opening of the fundamental circuit and the tandem units register is prepared for operation as soon as the fundamental circuit is again closed when the sequence switch 610 reaches position 4.

With sequence switch 610 in position 4 the fundamental circuit is closed through the windings of the control relay of the sender and the windings of stepping relay 500 of the testing device, the sender functioning to advance the tandem units register which reverts impulses back over the fundamental circuit for shunting the stepping relay 500. Stepping relay 500, upon energizing, closes a circuit for the No. 0 counting relay 502, it being assumed that the tandem units digit 0 has been selected. The circuit of relay 502 may be traced from battery, lower contact of cam 511 (4), winding of relay 502, No. 0 lead 513, lead 441 Fig. 4, inner left armature and contact of relay 428,

conductor 405, upper right contact of cam 514, conductor 516 to ground at the armature and contact of relay 500. Upon the first deenergization of relay 500 when the tandem units register advances one step, relay 503 energizes in parallel with relay 504 in the locking circuit of relay 502, relay 503 opening the fundamental circuit and relay 504 advancing the test switch 610 out of position 4 into position 5. As sequence switch 610 leaves position 4 the counting relays release. When sequence switch 610 reaches position 5 relay 652 becomes connected to the fundamental circuit, extending as traced to the sender over contacts of cams 620 and 624 and upon operating closes a circuit for relay 637 which in the manner previously described advances sequence switch 610 into position 6. Since resistances 676 and 680 are included in the circuit of relay 652, the control relay of the sender does not operate. As sequence switch 510 passes out of position 5, relays 652 and 637 release and the fundamental circuit extending through the windings of stepping relay 500 is again estab-

lished. From this point the testing device functions to set the numerical registers of the sender in exactly the same manner as hereinbefore described in connection with the tandem registration, the counting relays 70 being controlled over leads 442 to 446, inclusive, at the armature and contacts of relays 428 and 429 and over the contacts of cams 514 and 515 in positions 6, 8, 10, 12 and 14, respectively, of sequence switch 610. 75

As sequence switch 610 advances from position to position for controlling the several selections, lamps 654 to 658 become lighted and extinguished in succession, indicating that the several registrations are 80 successfully accomplished. When final units registration is completed, the fundamental circuit is opened by relay 503 and sequence switch 610 is advanced into position 15 as hereinbefore described. As sequence switch 610 leaves position 14 the operated counting relays are released and in position 15 circuits are established for the supervisory lamp 662, lamp 665 and lamp 661 as described in connection with previous tests. 90 The testing device now awaits the advance of the district selector.

At the sender associated with the district selector, as soon as the tandem registrations have been completed, the circuits function 95 to transfer such registrations to register control relays of the sender through the operation of the translator switch and impulse machine in the well known manner, whereupon a fundamental circuit is established 100 for controlling the brush selection operation of the district selector. This fundamental circuit may be traced in part from battery, right winding of relay 101, lower left contact of cam 145 (7), lower right contact of cam 146 (7 to 10), lower contact of cam 151, thence to the sender through the winding of the stepping relay thereof and to ground. Relay 101, upon energizing, closes a circuit 105 for advancing sequence switch 100 out of position 7 into position 8 which may be traced from battery, magnet winding of switch 100, lower left contact of cam 143 (7), left armature and front contact of relay 101 to ground at the left contacts of cam 139. In position 8 relay 101 is maintained 110 energized over a circuit from battery, its right winding inner right armature and front contact, lower left contact of cam 144 (2 to 13), lower right contact of cam 146 (7 to 10) and thence as described over the fundamental circuit to ground. The upper drive magnet 109 of the district selector is now energized and causes the upward movement of the district selector switch shaft 115 120 125 130 135 140 145 150 155 160 165 170 175 180 185 At the sender the stepping relay energizes in the well known manner and closes a circuit for a pair of counting relays. The updrive magnet 109, upon energizing, presses the depending portion of switch shaft 165 against the updrive drum 166 causing the switch shaft to be driven upwardly. As it approaches its first brush selection position, the shaft wiper 118 engages a metallic segment of commutator 113 and a circuit is closed from battery through the winding contact and inner right armature of relay 101, lower contact of cam 144, upper right contact of cam 145 (7 $\frac{3}{4}$ to 8), commutator 113, wiper 118, to ground, shunting the windings of the sender stepping relay. The stepping relay, upon deenergizing, operates the counting relays in succession until the sender is satisfied with respect to its district brush setting when the fundamental circuit is opened and the sender is prepared for district group selection. As soon following the opening of the fundamental circuit, as wiper 118 engages the next insulating portion of commutator 113, relay 101 de-energizes closing a circuit from battery through the magnet winding of switch 100, lower right contact of cam 143 (8), left armature and back contact of relay 101 to ground at the left contacts of cam 139 for advancing sequence switch 100 into position 9. Relay 101, upon deenergizing, also opens the circuit of updrive magnet 109 thereby arresting the movement of the switch shaft. With sequence switch 100 in position 9 a circuit is closed for the trip magnet 112 from battery, winding of magnet 112, upper right contact of cam 138 (9 to 10) to ground at the left contacts of cam 139. With sequence switch 100 in position 9 the fundamental circuit is again closed and relay 101 energizes in series with the stepping relay of the sender. Relay 101, upon energizing, closes the previously traced circuit for advancing sequence switch 100 out of position 9 into position 10. With relay 101 energized and sequence switch 100 in position 10 the circuit of the updrive magnet 109 is again established for driving the switch shaft 165 upwardly in its group selection movement. During the initial portion of this movement the selected brush set is tripped. As the switch shaft advances the shaft wiper 119 engages the conducting portions of commutator segment 114, closing momentarily a shunt around the windings of the stepping relay of the sender traceable from battery, right winding right armature and front contact of relay 101, lower contact of cam 144 (2 to 13), upper left contact of cam 145 (9 $\frac{3}{4}$ to 10), segment 114, wiper 119 to ground. Upon each establishment of this shunt the stepping relay of the sender deenergizes until the sender is satisfied with respect to its district group reg-

istration, when the fundamental circuit is opened and the sender is prepared for office brush selection.

As soon following the opening of the fundamental circuit as wiper 119 engages the next insulating segment of commutator 114, relay 101 deenergizes, opening the circuit of the updrive magnet 109 to arrest the group selection movement of the switch shaft, and closing the previously traced circuit for advancing sequence switch 100 into position 11. With sequence switch 100 in position 11 a circuit is established through the right winding of relay 101, lower left contact of cam 145 (11 to 12), lower left contact of cam 146 (11 to 11 $\frac{1}{4}$) to ground. Relay 101 attracts its armatures and closes the previously traced circuit for driving sequence switch 100 out of position 11 into position 12. Provided the first trunk in the group upon the terminals of which the brushes 120, 121 and 122 are standing is busy at this time, a ground potential is present on the test terminal and relay 101 remains energized in the following circuit: battery, left winding of relay 101, upper right contact of cam 135 (11 to 12), front contact and outer right armature of relay 101, lower contact of cam 141 (11 to 13), test brush 122 to grounded test terminal 168. A circuit is thereupon closed for the updrive magnet 109 and the brushes are advanced in a trunk hunting movement. When the test brush 122 encounters the test terminal 125 of the first idle trunk, relay 101 becomes deenergized and opens the circuit of updrive magnet 109 and also completes the circuit of sequence switch magnet 100 for advancing said sequence switch out of position 12 into position 13. On reaching position 12 $\frac{1}{2}$ sequence switch 100 applies ground potential to the test terminal 125 of the selected trunk to maintain the same non-selectable to all other switches. This potential is applied over a circuit from ground through the upper left contact of cam 139 (1 to 16), lower left contact of cam 137 (12 $\frac{3}{4}$ to 16 $\frac{1}{4}$) brush 122 to the test terminal 125.

It will be recalled that following units selection, sequence switch 610 of the testing device advances into position 15. In this position a circuit is established from ground at key 629, intermediate armature and front contact of relay 631, the upper winding of relay 634, the upper left winding of repeating coil 668, the upper contact of cam 624 (15), resistance 633, conductor 625, normal contacts of key ADJ, conductor 253, tip of jack 247, tip strand of cord 248, tip of jack 251, conductor 155, contacts of cam 130, the lower contact of cam 154 (1), and thence to the sender. In the well known manner a relay of the sender becomes energized in this circuit and closes

a circuit for relay 103 as soon as sequence switch 100 of the district selector reaches position 13 following trunk hunting. This circuit may be traced in part from battery, winding of relay 103, lower contact of cam 126 (13), conductor 164, lower right contact of cam 147 to ground at the sender. Relay 103, upon energizing, closes an obvious circuit for relay 105 which closes an obvious circuit for relay 104. Relay 104 now closes a circuit for relay 102 from battery, winding of relay 102, right contact of cam 128 (13 to 17), left armature and contact of relay 104 to ground. Relay 102, in turn, establishes a circuit from ground through its right armature and front contact, upper left contact of cam 134 (13 to 14), lower left contact of cam 134 (13), left armature and back contact of relay 101, lower right contact of cam 143 (12 to 13), winding of sequence switch magnet 100 to battery, driving sequence switch 100 out of position 13 into position 14.

With sequence switch 100 in position 14 relay 103 is maintained energized over a circuit which may be traced from battery through its winding, the upper contact of cam 126 and thence as previously traced through the upper winding of relay 634 to ground at key 629. Relay 634 operates in this circuit, closing a circuit from ground at its armature and front contact, through the left armature and back contact of relay 640 to battery through the winding of relay 639. Relay 639 now energizes locking over its right armature and front contact to ground at the lower right contact of cam 616 (15 to 16) and at its left armature and front contact closes a circuit for advancing sequence switch 610 into position 16. This latter circuit may be traced from battery, through the magnet winding of switch 610, lower right contact of cam 653 (15), left armature and front contact of relay 639, conductors 677, 678 and 679, contact of key 630, right contact of key 623 to ground at the lower contacts of cam 673 (15). When sequence switch 610 leaves position 15 lamp 665 is extinguished and the circuit through the winding of relay 634 and the winding of relay 103 is momentarily opened until sequence switch 610 reaches position 16. Upon the deenergization of relay 634 a circuit is closed for lamp 666 from battery through this lamp, upper right and lower left contacts of cam 667 to ground at the back contact of relay 634, but the lighting of lamp 666 may be disregarded at this time. When sequence switch 610 reaches position 16 relay 640 operates in a circuit from battery, winding of relay 640, lower contacts of cam 622 (16 to 17), conductor 677 to ground at the upper right contact of cam 669 (16), locking itself to ground over its inner right armature and front contact and at its outer right

armature and back contact opening the circuit of lamp 661.

At the district selector, with sequence switch 100 in position 14 a circuit is established from ground through the right armature and front contact of relay 102, upper left contact of cam 134 (13 to 14), lower right contact of cam 134 (14 to 15), lower right contact of cam 148 to battery through a relay winding of the sender, whereupon a circuit is established over the lower right contact of cam 149, upper right and lower left contacts of cam 136 (3 to 16), lower contact of cam 135 (14) to battery through the left winding of relay 101. Relay 101 is operated and establishes a circuit from battery through the winding of sequence switch magnet 100, the lower left contact of cam 143 (14), front contact and left armature of relay 101, lower left contact of cam 139 (14), upper left contact of cam 139 (1 to 16) to ground, driving said sequence switch out of position 14 into position 15.

To prevent sequence switch 610 of the testing device from prematurely advancing from position 15 to cause the advance of sequence switch 100 of the distant district selector out of position 13 before the distant-district sender is ready for such operation, relay 636 of 12,000 ohms resistance is connected in series with the winding of relay 635, over the lower armature and front contact of relay 631, the lower winding of relay 634, the lower left winding of repeating coil 668, the lower contact of cam 620, resistance 632, conductor 652, ring of jack 247, ring strand of cord circuit 248, ring of jack 251, conductor 156 to the ring conductor of the distant-district circuit. Under this condition should ground be connected to the ring conductor of the distant-district before battery is connected to the tip conductor of the district at the contacts of cam 126, relay 636 operates, but relays 635 and 634 do not operate, and relay 636 closes a circuit for the overflow lamp 535 indicating a trouble condition. The circuit of lamp 535 may be traced from battery through lamp 535, conductor 552 to ground at the armature and contact of relay 636.

With sequence switch 100 of the distant district selector 150 in position 15, a fundamental circuit is established between the district sender and the office selector 250 which may be traced in part from battery, right winding of control relay 200, lower left contact of cam 203 (1), upper left contact of cam 201 (1 to 4), conductor 239, terminal 123, brush 120, lower contacts of cam 152, lower contact of cam 151 (1), thence through the control circuit of the sender returning through the lower contact of cam 162 (1), lower contacts of cam 157, brush 121, terminal 124, conductor 240 to ground at the contact of cam 202 (1 to 4). The office

selector is now controlled from the sender in its brush and group selection movements in the well known manner in accordance with the office brush and office group portions of the tandem registrations recorded upon the registers of the sender. When such selections are completed the office selector proceeds to hunt for an idle trunk extending to a final selector. For the purpose of this 10 description it will be assumed that the final selector 350 is selected.

The incoming brush, incoming group, final brush, final tens and final units selections are now accomplished at the final selector switch 15 350 in the manner fully set forth in the patent to E. W. Hancock above referred to and in accordance with the numerical registrations recorded upon the registers of the district sender, the selector switch 350 being directed as hereinbefore described to select the terminals of the test line 344, 345, and 346. Following the completion of final units selection the sequence switch of the sender advances in the well known manner closing a 20 circuit over the lower contact of cam 143 (1), the lower contacts of cam 134, the left armature and back contact of relay 101, the lower right contact of cam 143 to battery through the magnet winding of sequence 25 switch 100 for advancing this switch from position 15 into the talking position 16. The sender is thereupon released from the connection in the manner set forth in the aforesaid patent to E. W. Hancock.

30 When the test brush 340 of the final selector engages the test terminal 343 of the test line, a circuit is established as hereinbefore traced for the test relay 302 of the final selector and for relay 601 of the testing device, relay 302 functioning to advance the sequence switch 310 of the final selector into the talking position 16. Relay 601 performs no useful function at this time as relay 640 is already operated. With sequence switch 40 310 of the final selector in position 16 a circuit is now established for relay 643 from battery, left winding of relay 643, right armature and normal contact of relay 645, ring of jack 243, ring strand of cord 242, 45 ring of jack 238, conductors 231 and 345, terminal 342, brush 339, upper contact of cam 307 (16), conductor 233, terminal 228, brush 216, upper contacts of cam 204 (8), conductor 240, terminal 124, brush 121, 50 lower right and upper left contacts of cam 157, outer right armature and front contact of relay 105, windings of polarized relay 106, upper left and lower right contacts of cam 156, brush 120, terminal 123, conductor 55 239, upper contacts of cam 201 (8), brush 215, terminal 227, conductor 232, lower left contact of cam 305, lower left contact of cam 306 (16), brush 338, terminal 341, conductor 344, conductor 230, tip of jack 238, tip strand 60 of cord 242, tip of jack 243 to ground at the

left normal armature contact of relay 645. Relay 643, upon energizing, closes a locking circuit for itself from battery through its right winding, right armature and contact to ground at the upper left contact of cam 70 669 (1 to 16), closes a circuit for lamp 670 through the same armature contact and establishes an obvious circuit for relay 644 through its left armature and contact. The lighting of lamp 670 is an indication to the 75 test-man that the answering key ANS should be operated. Relay 644, upon energizing, closes at its inner right armature and contact a short circuit around the winding of relay 636 which may be traced from battery, inner right armature and contact of relay 644, through the winding of relay 636 to battery. Relay 636 now releases if it was previously operated, extinguishing the lamp 80 535.

When the test-man operates the key ANS a circuit is established from ground at the left contact of relay 644, contact of key ANS to battery through the winding of relay 645, which thereupon reverses ground and battery connections to the circuit previously traced through the windings of polarized relay 106. The current now flowing through the windings of relay 106 is in the proper direction to cause its operation, whereupon 90 a circuit is closed from ground at the armature and contact of relay 106, through coil 107, the inner right armature and contact of relay 105, the upper contact of cam 127 (15 to 17), thence over conductor 156 and as 95 previously traced through the lower winding of relay 634, the winding of relay 635 to battery at the inner right armature and contact of relay 644. Relay 634 is at this time operated by reason of current flowing 100 through its upper winding and the winding of relay 103 at the district selector, but relay 635 now energizes opening the circuit of supervisory lamp 662 and at its armature and front contact closing a circuit for relay 110 638. This latter circuit may be traced from ground at the lower right contact of cam 616 (15 to 17), the armature and front contact of relay 635, winding of relay 638 to battery at the outer armature and contact of relay 644. Relay 638, upon operating, closes a circuit for relay 646 from battery, winding of this relay, armature and contact of relay 638 to ground at the lower right contact of cam 669 (16). Relay 646 now 115 locks to ground at cam 669 through its inner left armature and contact and prepares a circuit for the start relay 608.

The test-man observing that the supervisory lamp 662 is extinguished, indicating 120 that the answering condition has been successfully performed at the distant district selector, operates the start key 607 closing a circuit from battery, through the winding of start relay 608, inner right armature and 125 130

front contact of relay 613, conductor 614, contact of key 607 to ground at the inner right armature and contact of relay 646. Relay 608, upon energizing, locks in series with relay 617, this latter relay operating as soon as the start key 607 is released. When relay 617 energizes the sequence switch 610 is advanced to position 17. When sequence switch 610 leaves position 16 the holding circuits of relays 608, 617, 643 and 644, 645, 646, 635, 638 and 613 are opened and lamp 670 is extinguished. Upon the release of relay 645 current is again reversed to the district selector and polarized relay 106 retracts its armature disconnecting ground from the ring conductor 156. Relay 635, now deenergizes, closing the circuit of supervisory lamp 662 which now serves to give a disconnect signal. The test man now releases the "distant district" key 612 and depresses the disconnect key 672. When the key 612 is released, relays 619, 631, 428 and 429 release. The operation of disconnect key 672 closes a circuit for relay 641 from battery, winding of relay 641, contact of key 672 to ground at the upper right contact of cam 609. Relay 641, upon energizing, locks to ground at cam 609 through its right armature and contact and at its inner left armature and contact closes a circuit from ground at cam 609, through the inner left armature and contact of relay 641, upper left contact of cam 618 (2 to 18) to battery, through the magnet winding of sequence switch 610 for advancing sequence switch 610 into normal position 1. When sequence switch 610 leaves position 17 the circuit previously traced through the upper winding of relay 634 and the winding of relay 103 is opened and these relays release. Relay 103, upon releasing, opens the circuits of relays 102, 104 and 105, permitting these relays to also release. Relay 102 at its right armature and back contact now closes a circuit through the magnet winding of sequence switch 100 for driving it out of position 16 into position 18. The circuit of the downdrive magnet 111 is now established from battery, winding of magnet 111, lower left contact of cam 138 (18) to ground at the upper left contact of cam 139 (18). Magnet 111, upon energizing, now presses the depending portion of the switch shaft 165 against the downdrive drum 167, driving the switch shaft downwardly into normal position, whereupon a circuit is established for advancing sequence switch 100 out of position 18 into normal position 1. This circuit may be traced from battery, magnet winding of switch 100, upper right contact of cam 132 (9 to 18), normal segment 116, wiper 117 to ground.

When sequence switch 100 leaves position 17 the circuit previously traced through the upper winding of relay 634 and the winding of relay 103 is opened and these relays release. Relay 103, upon releasing, opens the circuits of relays 102, 104 and 105, permitting these relays to also release. Relay 102 at its right armature and back contact now closes a circuit through the magnet winding of sequence switch 100 for driving it out of position 16 into position 18. The circuit of the downdrive magnet 111 is now established from battery, winding of magnet 111, lower left contact of cam 138 (18) to ground at the upper left contact of cam 139 (18). Magnet 111, upon energizing, now presses the depending portion of the switch shaft 165 against the downdrive drum 167, driving the switch shaft downwardly into normal position, whereupon a circuit is established for advancing sequence switch 100 out of position 18 into normal position 1. This circuit may be traced from battery, magnet winding of switch 100, upper right contact of cam 132 (9 to 18), normal segment 116, wiper 117 to ground.

test terminal 125 and the release of the office selector is initiated. The office selector and final selector now release in the manner previously described. All apparatus employed in the test of the distant-district is now in normal position and if no further tests are to be made on the district selector, the cord circuit 248 is detached from the make-busy jack 251 of the district selector.

If while the testing circuits are established from the testing device through the distant district to the test line, the test-man wishes to test the district for flashing or ringing, the key 629 is operated opening the circuit traced through the upper winding of supervisory relay 634 and the winding of relay 103 of the district selector. Relay 103, thereupon, releases, opening the circuit of relay 105 causing it to release, in turn, opening the circuit of the polarized relay 106 causing it to release. When the polarized relay 106 releases it disconnects ground from the ring conductor of the district circuit, releasing relay 635 of the testing device which then closes the circuit of supervisory lamp 662. When the key 629 is released, relays 103, 105, 106, 634 and 635 again operate, relay 635 extinguishing the lamp 662. For each operation and release of key 629, lamp 662, therefore, is lighted and extinguished indicating if the relays 103, 105 and 106 of the district selector function as they should. If it is desired to test relay 103 of the district selector, key ADJ of the testing device is operated, opening a circuit through the winding of relay 103. The test-man may now plug up a relay testing circuit in the jack 686, the ring contact of which is connected to conductor 253 and thence as previously traced to battery through the winding of relay 103.

Should the district selector go to overflow during trunk hunting, its sequence switch is advanced to the overflow position 17 and the polarized relay 106 is then included in a circuit from battery through the interrupter 108, upper contacts of cam 152, winding of relay 106, outer right armature and contact of relay 105 to ground through the upper contacts of cam 157. Polarized relay 106 now intermittently connects ground to the ring conductor of the district circuit whereby relay 636 at the testing device is intermittently operated to flash the overflow lamp 535 for indicating an overflow condition.

Testing office selector in conjunction with final selector-continuous testing method.

To test the office selector in conjunction with the final selector by the continuous testing method, the "step-by-step" key 611 and the "exercise" key 627 are retained in their

When sequence switch 100 leaves position 16₁ ground potential is removed from the

Testing office selector in conjunction with final selector-continuous testing method. 125

To test the office selector in conjunction with the final selector by the continuous testing method, the "step-by-step" key 611 and the "exercise" key 627 are retained in their normal unoperated positions and the testing 130

device functions in the manner previously described under the step-by-step method with the following exceptions: After the start key 607 has been operated to start the 5 test, it is released and is not again operated during the test. The operation and release of key 607 advances sequence switch 610 into position 2 in which position a circuit is established for relay 642 from battery, 10 winding of relay 642, normal contact of key 611 to ground at the lower left contact of cam 650 (2 to 16). Relay 642 thereupon locks to ground at the outer left armature and back contact of relay 641. When sequence 15 switch 610 reaches positions 3, 7, 9, 11 and 13 following each digit selection, it is automatically advanced into positions 4, 8, 10, 12 and 14, respectively, without waiting for the re-operation of start key 607, over a circuit 20 from battery, magnet winding of sequence switch 610, lower left contact of cam 618, lowermost normal contact of key 611, outer right normal contact of key 621 to ground at the outer left normal contact of key 628. 25 Following units selection, the sequence switch 610 advances to position 15 from whence it is advanced to position 16 through the operation of relays 663 and 640 as previously described and to position 17 over a 30 circuit from ground at the inner contact of key 611, inner left armature and contact of relay 642, lower right contact of cam 649 (16) to battery through the winding of sequence switch magnet 610. From position 35 17 the sequence switch is advanced into normal position as previously described through the operation of the disconnect key 672. It is thus apparent that under this method of testing the complete test is made with a 40 single operation of the start key.

The office selector is tested under this method in conjunction with trunks to full mechanical or semi-mechanical offices or with trunks to manual offices in substantially the 45 same manner as described under the step-by-step method except that the sequence switch 610 is automatically advanced without the reoperation of the start key 607 as described in the preceding paragraph.

50 To test a final selector only by this method the same procedure is followed as under the step-by-step method except that the key 611 is not operated. Consequently, when the start key 607 is operated sequence switch 55 610 advances into position 2 causing the locking up of relay 642. With the "final only" key 623 operated, sequence switch 610 now advances directly into position 6 as previously described, omitting office selections. From this point the test proceeds automatically through a single cycle.

In testing the distant-district selector by the continuous method, the circuit functions as previously described in connection with 60 the test of the distant-district under the

step-by-step method except that the sequence switch 610 is advanced to position 2 automatically following the testing of the selected district for its busy or idle condition without a reoperation of the start key 607. This result is attained since at this time, as will be recalled, relay 642 is operated and a circuit is, therefore, effective from battery, magnet winding of sequence switch 610, lower right contact of cam 649 (1), inner left armature and contact of relay 642 to ground at the normal contact of key 611. Following the various selections, sequence switch 610 is automatically advanced out of positions 3, 7, 9, 11 and 13 into positions 4, 8, 10, 12 and 14 from battery through the winding of sequence switch magnet 610, lower left contact of cam 618, normal contact of key 611 to ground through the normal contact of keys 621 and 628.

Testing selectors by the exercise method.

Under this method of testing the "exercise" key 627 is operated and the "step-by-step" key 611 is retained in its normal position. The circuit now functions for the various tests in the same manner as under the step-by-step method except that when the sequence switch 610 reaches position 17, 95 it is immediately advanced in a further cycle by reason of a circuit from battery, magnet winding of switch 610, upper right contact of cam 618 (16 to 1), outer left armature and contact of relay 642, contact of key 627 to ground at the right contact of cam 684 (17 to 1). The test being conducted is, therefore, repeated through cycle after cycle until the test-man operates the disconnect key 672, when the locking circuit of relay 642 is opened at the outer left armature and normal contact of relay 641, thereby opening the circuit for advancing sequence switch 610 through the normal position.

The test-man may control the starting and stopping of the testing device from a distant point by connecting plug ended controlling circuits (not shown) into the jacks 687 and 688, the contacts of jack 687 being in multiple with contacts of disconnect key 672 and the contacts of jack 688 in multiple with the contacts of start key 607. Each of these controlling circuits may terminate at their distant ends in suitable controlling keys. By this means the test-man may control the testing device while maintaining a position among the selector switch frames for watching the operation of the particular switch or switches under test.

While in the foregoing description the invention has been described in connection with certain specified test calls for obtaining connections through the selectors under test to particular called lines or to test lines,

it will be obvious that the test-man may record the designation of any line terminating in the exchange area upon the keyboard of the testing device whereupon the 5 testing device will function to control the extension of a connection to the terminals of the line so designated.

What is claimed is:

1. In a telephone exchange system, a testing device for testing selector switches, means for connecting said testing device with one of said switches, a test line extending from the terminal bank of said switch to said testing device, a sender at said testing 10 device for setting said switch upon the terminals of said test line, a plurality of signals for indicating if the selector progresses properly in its selective movements, and supervisory means operative over said test line.
2. In a telephone exchange system, a testing device for testing selector switches, means for connecting said testing device with one of said switches, a test line extending 15 from the terminal bank of said switch to said testing device, a sender at said testing device for setting said switch upon the terminals of said test line, a supervisory signal at said testing device, means for operating said signal upon completion of the 20 operation of said sender, means at said switch for effacing said signal during the line testing function of said switch, and means effective over said test line for reoperating said signal.
3. In a telephone exchange system, a testing device for testing selector switches, means for connecting said testing device with one of said switches, a test line extending 25 from the terminal bank of said switch to said testing device, a sender at said testing device for setting said switch upon the terminals of said test line, a supervisory signal at said testing device, means effective over said test line upon the seizure thereof by said switch for operating said signal, and means at said testing device for simulating the answering of a call over the test line for effacing said signal.
4. In a telephone exchange system, a testing device for testing selector switches, means for connecting said testing device with one of said switches, a test line extending 30 from the terminal bank of said switch to said testing device, a sender at said testing device for setting said switch upon the terminals of said test line, a polarized supervisory relay at said testing device, a supervisory signal under the control thereof, means for operating said signal upon the completion of the operation of said sender, means at said switch for operating said relay to efface said signal during the line testing function of said switch, and means for 35 reversing current over said test line whereby said relay causes the reoperation of said signal.
5. In a telephone exchange system, a testing device for testing selector switches, means for connecting said testing device with one of said switches, a test line extending from the terminal bank of said switch to said testing device, a sender at said testing device for setting said switch upon the terminals of said test line, a polarized supervisory relay at said testing device, a supervisory signal under the control thereof, means for operating said signal upon the completion of the operation of said sender, means at said switch for operating said relay to efface said signal during the testing function of said switch, means at said testing device for applying reverse current over said test line whereby said relay causes the reoperation of said signal, and a key at said testing device for again reversing current over said test line for again effacing said signal.
6. In a telephone exchange system, a testing device for testing selector switches, means for connecting said testing device with one of said switches, a test line extending from the terminal bank of said switch to said testing device, a sender at said testing device for setting said switch upon the terminals of said test line, a line testing relay at said switch, a relay at said testing device operable over said test line in series with said testing relay if the line testing circuits of said switch are in standard condition, and a signaling device controlled by the relay of said testing device.
7. In a telephone exchange system, a testing device for testing selector switches, means for connecting said testing device with one of said switches, a test line extending from the terminal bank of said switch to said testing device, a sender at said testing device for setting said switch upon the terminals of said test line, means at said switch for connecting battery and ground through the talking conductors of said selector circuit, a relay at said testing device responsive to said battery and ground connections, a second relay operable over said test line, a signal, and a circuit for said signal closed upon the operation of said second relay, and the failure of said first relay to operate, said signal indicating that a fault has occurred in said battery and ground connecting means at said switch.
8. In a telephone exchange system, a testing device for testing a selector switch, means for connecting said testing device with said switch, a test line extending from the terminal bank of said switch to said testing device, a sender at said testing device for setting said switch upon the terminals of said test line, a relay at said testing device operable over the talking conductors

and brushes of said switch and over conductors of said test line, a signal, and a circuit for said signal extending through contacts of said relay, said signal operating upon the 5 failure of said relay to energize for indicating an unstandard circuit condition in the talking conductors or at the brushes of said switch.

9. In a telephone exchange system, a testing device for testing selector switches, means for connecting said testing device with one of said switches, a test line extending from the terminal bank of said switch to said testing device, a sender at said testing 10 device for setting said switch upon the terminals of said test line, a circuit extending from said testing device over the tip and ring conductors and brushes of said switch and over conductors of said test line back 15 to said testing device, two relays at said testing device, both operative over said circuit if said circuit is closed at said switch and one only of said relays operative if said circuit is grounded on the tip side or short circuited at said switch, and signals at said 20 testing device under the control of said relays for indicating the condition of said circuit of said switch.

10. In a telephone exchange system, a testing device for testing selector switches, means for connecting said testing device with one of said switches, a test line extending from the terminal bank of said switch to said testing device, a sender at said testing 30 device for setting said switch upon the terminals of said test line, a circuit extending from said testing device over the tip and ring conductors and brushes of said switch and over conductors of said test line back 35 to said testing device, a polarized relay and a second relay at said testing device, means at said testing device for reversing the current flowing in said circuit, said relays both operative over said circuit 40 if said circuit is closed at said switch and only said second relay being operative if the ring side of said circuit is grounded at said switch, and signals under the control of said relays for indicating the condition of 45 said circuit at said switch.

11. In a telephone exchange system, a testing device for testing selector switches, a circuit for connecting said testing device with one of said switches, a test line extending 50 from the terminal bank of said switch to said testing device, a sender at said testing device for setting said switch upon the terminals of said test line, a key at said testing device for placing busy test potential upon the test terminal of said test line, means at said switch responsive to said busy potential for connecting a source of busy signaling current to said connecting current, and signaling means at said 55 testing device responsive to said busy sig-

naling current for indicating if said switch functions correctly in testing busy lines.

12. In a telephone exchange system, a testing device for testing selector switches, a circuit for connecting said testing device 70 with one of said switches, a test line extending from the terminal bank of said switch to said testing device, a sender at said testing device for setting said switch upon the terminals of said test line, a key 75 at said testing device for placing busy test potential upon the test terminal of said test line, means at said switch responsive to said busy potential for connecting a source of busy signaling current to said connecting current, a relay at said testing device responsive to said busy signaling current, and a lamp signal controlled by said relay for indicating if said switch functions correctly in testing busy lines. 80

13. In a telephone exchange system, a testing device for testing selector switches, a circuit for connecting said testing device with one of said switches, a test line extending from the terminal bank of said switch to said testing device, a sender at said testing device for setting said switch upon the terminals of said test line, a key at said testing device for placing potential upon the test terminal of said test line in simulation 90 of the condition encountered by said switch in actual service in testing a busy first line of a group of lines allotted to a private branch exchange, means at said switch for causing said switch to hunt for 100 an idle line in response to said busy potential, and means at said testing device for indicating if said switch has so functioned.

14. In a telephone exchange system, a testing device for testing selector switches, 105 a circuit for connecting said testing device with one of said switches, a test line extending to said testing device, means including said selector switch for extending a connection to said test line, a bridge across 110 the talking conductors of said switch, means at said switch for opening and closing said bridge, a supervisory relay at said testing device controllable over said test line and the bridge at said selector switch, a signaling 115 device controlled by said supervisory relay, and means at said testing device for controlling said means at said switch in simulation of flashing and reringing operations whereby said signaling means is 120 caused to indicate if said switch functions correctly in controlling these operations.

15. In a telephone exchange system, a testing device for testing selector switches, a circuit for connecting said testing device 125 with one of said switches, a test line extending to said testing device, means including said selector switch for extending a connection to said test line, a bridge across the talking conductors of said switch, means at 130

- 12 said switch for opening and closing said bridge, a supervisory relay at said testing device controllable over said test line and the bridge at said selector switch, a signaling device controlled by said supervisory relay, and a key at said testing device for controlling said means in simulation of flashing and reringing operations whereby said signaling means is caused to indicate if said switch 5 functions correctly in controlling these operations.
- 13 16. In a telephone exchange system, a testing device for testing selector switches, a circuit for connecting said testing device 15 with one of said switches, a test line extending to said testing device, means including said selector switch for extending a connection to said test line, a bridge across the talking conductors of said switch including 20 a polarized relay, a supervisory relay at said testing device under the control of said polarized relay over said test line, a signaling device under the control of said supervisory relay, and means at said testing device for 25 controlling said polarized relay over said test line, said signaling device functioning to indicate if said polarized relay operates correctly.
- 14 17. In a telephone exchange system, a testing device for testing selector switches, a circuit for connecting said testing device with one of said switches, a test line extending to said testing device, means including 30 said selector switch for extending a connection to said test line, a bridge across the talking conductors of said switch including a relay, means controlled by said switch for intermittently operating said relay if said switch is driven to its overflow position, and a supervisory relay at said testing 35 device under the control of said first relay over said test line, a signaling device under the control of said supervisory relay, said signaling device when intermittently operated through the operation of said first relay indicating that said switch functions correctly under overflow conditions.
- 15 18. In a telephone exchange system, a testing device for testing selector switches, a circuit for connecting said testing device with one of said switches, a sender at said testing device for controlling the setting of 40 said switch over said circuit, a relay associated with said sender, a signaling device controlled by said relay, and means at said switch operative if said switch is driven to its overflow position for operating said relay whereby said signaling device is caused to indicate that said switch functions correctly upon encountering an overflow position.
- 16 19. In a telephone exchange system, a testing device for testing selector switches, a circuit for connecting said testing device with one of said switches, a sender at said 45 testing device for controlling the setting of said switch over said circuit, a polarized relay at said sender in said circuit, a lamp controlled by said relay, and means at said switch operative if said switch is driven to its overflow position for operating said relay whereby said lamp is caused to indicate that said switch functions correctly upon encountering an overflow position.
- 17 20. In a telephone exchange system, a testing device for testing selector switches, a circuit for connecting said testing device with said switches, a sender including a keyboard at said testing device for controlling the selective operations of said switches in accordance with the designations of test calls recorded upon said keyboard, means for advancing a test call through its several stages, and a key for controlling said means following completion of each of said stages.
- 18 21. In a telephone exchange system, a testing device for testing selector switches, means for connecting said testing device with said switches, a keyboard, a sender arranged to control the several selective operations of said switches in accordance with designations recorded upon said keyboard, a multi-position test controlling switch, and a key for advancing said controlling switch upon the completion of each selection controlled by said sender.
- 19 22. In a telephone exchange system, a testing device for testing selector switches, means for connecting said testing device with said switches, a keyboard, a sender arranged to control the several selective operations of said switches in accordance with designations recorded upon said keyboard, a multi-position test controlling switch adapted during a single revolution to control the several stages of a test, a key for starting said controlling switch into operation, means for automatically advancing said controlling switch upon the completion of each selective control by said sender, and a key for preventing the further advance of said controlling switch after it has completed a single revolution.
- 20 23. In a telephone exchange system, a testing device for testing selector switches, means for connecting said testing device with said switches, a keyboard, a sender arranged to control the several selective operations of said switches in accordance with designations recorded upon said keyboard, a multi-position test controlling switch adapted during a single revolution to control the several stages of a test, a key for starting said controlling switch into operation, means for automatically advancing said controlling switch upon the completion by said sender of each selection control, and a key for permitting the advance of said controlling switch through successive revolutions for re-

peating the same test upon selector switches under test.

24. In a telephone exchange system, a testing device for testing selector switches, 5 means for connecting said testing device with any one of said switches, means at said testing device for testing certain of said switches singly and certain others of said switches in conjunction with other switches 10 and means for indicating if said switches function accurately in response to such tests.

25. In a telephone exchange system, a testing device for testing a selector switch, means for connecting said testing device

with said switch, a test line extending from 15 the terminal bank of said switch to said testing device, a sender at said testing device for setting said switch upon the terminals of said test line, means at said testing device operative if said switch fails to establish a 20 conductive loop circuit over the conductors of said test line, and means at the testing device for determining the character of the un-standard condition of said switch.

In witness whereof, I hereunto subscribe 25 my name this 21 day of December A. D. 1922.

ERIC R. LUNDIUS.
